UNITED STATES PATENT OFFICE

1,942,462

TELEPHONE SYSTEM

John Wicks, Oak Park, Ill., assignor to Automatic Electric Company, Limited, Liverpool, England

Application July 16, 1932. Serial No. 622,909

41 Claims. (Cl. 179—18)

The present invention relates in general to telephone systems, but is concerned more particularly with automatic telephone systems, and the object of the invention is to produce a new and improved automatic telephone system employing suitably controlled single-motion rotary step-by-step mechanisms.

GENERAL DESCRIPTION

Following the general recognition of the Strowger, automatic, vertical-and-rotary switch, together with systems incorporating this switch for use in setting up connections between calling and called lines, many attempts have been made to replace the vertical-and-rotary Strowger mechanism with a mechanism having a rotary motion only, on the theory that a switch mechanism which has only a single motion is inherently simpler and more economical to produce than one which has two coordinate motions. Further, these attempts have been based partly on the belief that more flexibility is secured with a rotary mechanism, as regards the allocation of contacts to trunk groups, as the division of the contacts in the trunk groups in a rotary mechanism may be made along purely arbitrary lines, whereas with the Strowger mechanism (as commonly employed) the grouping is rather rigidly determined in accordance with the separate levels of contacts.

Whereas the group selection is determined by a primary, or group selecting, ordinate motion in a Strowger switch, bringing the wipers of the switch opposite a desired level of bank contacts directly responsive to received incoming impulses constituting a series; in the case of a switch mechanism having a rotary motion only, with all of the contact sets arranged in one row or level, the advance of the wipers into association with the desired group of contacts must be made by a hunting movement, and this hunting movement must be controlled by an impulse responder or register of some suitable form, and the wipers are subsequently rotated over the contacts in the group in a trunk-hunting operation, or in response to the final digit in the number, as in the case of a connector or final selector.

As an alternative to the above-described method of bringing about the group positioning of the rotary switch, a so-called register sender may be employed at a point more or less remote from the switches, in which register sender the digits of a desired number are stored, following which the serially related rotary switches are successively positioned by revertive control, somewhat

after the fashion of the power driven automatic switches.

For the purpose of combining economy with reliability both of the above-enumerated methods of positioning the rotary switches are made use of in the system herein disclosed; the connectors, or final selectors, are positioned, in tens selection under revertive control, while the group selectors are positioned by a hunting operation.

A feature of the system disclosed herein in that apparatus common to the several groups of switches is provided for the purpose of enabling the individual switch mechanisms and relay apparatus to be simplified and abbreviated as much as possible.

A further feature of the present disclosure is that the common-apparatus unit for a group of selectors includes what is termed a by-pass selector, which is arranged to quickly find an idle trunk in a selected group and to extend a dialling connection immediately thereto so that the next digit dialled will be delivered to its proper destination, while the associated conversational switch is caused to hunt for and connect with the same trunk line engaged by the by-pass selector, whereupon the connection is made through the conversational switch, and the by-pass selector and associated common equipment are released.

The invention includes a number of features of novelty in a system such as briefly outlined above, and will appear more fully hereinafter.

Description of drawings

Referring now to the accompanying drawings, comprising Figs. 1 to 9, they show by means of the usual circuit diagrams a sufficient amount of the equipment in a telephone system embodying the invention to enable the invention to be understood. More in particular, Figs. 1 to 4, show switching apparatus through which a connection may be set up from the line substation A, Fig. 1, to the line of substation B, Fig. 4; Figs. 5 to 8 show certain common controlling equipment which is taken into use temporarily while the connection is being established but which forms no part of the established talking connection; and Fig. 9 shows an overflow circuit, the utility for which will be made apparent hereinafter.

The invention has been illustrated in connection with a ten-thousand-line system, one employing three orders of numerical switches. The first order of numerical switches is represented by the first selector FS—1, Fig. 2 (a thousands selector); the second order of switches is repre-

110

sented by the penultimate selector PU—1, Fig. 3, (a hundreds selector); and the final order of switches is represented by the connector, or final selector C—1, Fig. 4.

5 The non-numerical trunking, the trunking between calling lines and the first selectors, is accomplished by finder-secondary links, one of which is illustrated in Fig. 1 as the finder F and the secondary switch SS. As regards calling, the 10 subscribers' lines are divided into groups of approximately one hundred lines each. The line finders, of which the finder F, Fig. 1, is an example, may each have access to a total of 102 lines, having for this purpose six semi-circles of 15 bank contacts, fifty-one contacts in a semi-circle, with a single ended wiper for each semi-circle of bank contacts, as illustrated. The wipers are 20 divided into two groups as shown, and positioned so as to stand in diametrically opposite positions. The wipers are interconnected in pairs, giving the effect of three wipers having access to 102 bank contacts each.

25 The finder F is provided with a single operating magnet, magnet 114. This magnet is arranged to be operated in a buzzer-like manner through the control of its associated interrupter contacts, and it advances the wipers 108—113 one step each time it restores after having been operated.

30 The secondary switch SS is of similar construction to the finder F, but it is provided with only three semi-circles of bank contacts of twenty-five contacts to each semi-circle and with three cooperating double-ended wipers, actuated by the operating magnet 134.

35 In order to provide an economical distribution of traffic, the distributing frame DF is interposed between the finders, such as F, and the secondary switches, such as SS, so as to allow the calls originated in a single finder group to be 40 distributed throughout a number of groups of secondary switches. Each secondary switch has access to twenty-five first selectors, such as the first selector FS1, Fig. 2. The first selectors are ordinarily mounted and bank wired in groups of 45 ten. Therefore, a group of secondary switches, such as SS, have their banks connected in multiple and connected to two and one-half groups or shelves of first selectors. The next two and one-half shelves of first selectors are accessible 50 to a second group of secondary switches, and so on.

55 Keeping in mind that the finders, such as F, are provided in sufficient numbers in each case to handle the maximum estimated traffic from the associated group of calling lines, it may now be pointed out that the distributing frame DF is utilized about as follows. The terminals corresponding to the first finder in a group may be cross-connected on the distributing frame DF to 60 a secondary switch in the first secondary group; the second finder in the same group may be cross-connected to a switch in the second secondary group; and so on. Other groups of finders are connected to these secondary groups in a similar 65 manner. In this way, a given secondary group receives calls from a large number of finder groups, whereby the traffic amongst the several secondary groups is substantially equalized, although the traffic furnished by the several primary or finder groups may differ from group to 70 group at any given time.

75 For the purpose of controlling the finder switches and secondary switches, a pair of distributors is provided for each finder group. The distributors D1 and D2, Fig. 5, are the distributors

provided for the finder group containing the finder F, Fig. 1. These distributors are controlled over the start wire 150 common to all of the lines accessible to the finder F and associated finders. Each distributor comprises a rotary switch mechanism having eight double-ended wipers, with twenty-five contacts in each semi-circle of bank contacts. Ordinarily, there are only from ten to fifteen finders in a group, in which case the unused contact sets are passed over by the distributor because the test contacts of the unused sets are connected to ground. The distributors D1 and D2 are arranged so that they operate concurrently, each of them taking a second finder secondary link for use pursuant to 80 linking the calling line to an idle first selector, and the first to complete this operation causes the other distributor to stop, unless a second line is calling, in which case the second distributor continues its operation to cause the second calling line to be linked with an idle first selector. 85

90 The first selectors, represented by the first selector FS1, Fig. 2, are each similar to the finder F, Fig. 1, except that eight pairs of wipers and eight fifty-one contacts of semi-circles are provided, as 95 there are four conductors in the bank multiple of the selectors instead of three, as in the case of the finders. The selector has access to approximately one-hundred trunk lines, which are ordinarily divided into ten groups averaging ten 100 trunk lines to a group, although the sizes of the groups may be assigned so that some groups contain only a few trunks, while other groups contain more than ten, depending upon traffic requirements and other practical considerations. 105

110 As mentioned before, the first selectors are ordinarily mounted in groups of ten, called a "shelf". A pair of by-pass selectors, the by-pass selectors, such as BPS—1 and BPS—2, Fig. 6, are provided for each shelf of ten selectors. A 115 permanent bank multiple is provided which multiples together the bank contacts of all the selectors in a shelf and the bank contacts of the two by-pass selectors of the same shelf. Whereas the selectors through which the conversational 120 connections are established are provided with single-ended paired wipers and have no normal position, the by-pass selectors, such as the selector BPS—1, Fig. 6, are provided with double-ended 125 wipers and have a normal position, corresponding to the fifty-first set of bank contacts.

130 The ten selectors of a shelf are divided into two sub-groups of five selectors each, with a separate one of the two by-pass selectors associated with each of the two sub-groups. Each of the five 135 selectors of a sub-group is normally connected to the associated by-pass selector, whereby when a selector is taken for use the remaining idle selectors in the same sub-group are rendered temporarily busy to the switches having access to them. Following this, the by-pass selector receives the digit in accordance with which the selector is to be positioned and selects an idle trunk line in the corresponding group, following which the selector used is caused to hunt for and connect with the same trunk line, whereupon the by-pass selector is freed and the remaining idle 140 selectors in the same sub-group are rendered available for service. A convenient way of dividing the ten selectors of a shelf into sub-groups corresponding to the two by-pass selectors BPS—1 and BPS—2, Fig. 6, is to assign the first selector FS1, Fig. 2, and each of the odd-numbered 145 selectors to the by-pass selector BPS—1 and to assign the selector FS2, Fig. 2, and each 150

of the even-numbered selectors of the shelf to the by-pass selector BPS-2, Fig. 6. This is the arrangement indicated in Figs. 2 and 6. Interference between simultaneous position tests being 5 performed in two sub-groups of a shelf is prevented by the arrangement whereby the switches in one sub-group test for the position assumed by the associated by-pass switch by searching for one pole of the exchange battery, while the 10 switches in the other sub-group of the shelf test for the other pole of the exchange battery.

The register RS associated with the by-pass selector BPS-1 is a ten-point rotary switch having the double-ended wiper 641, driven on the 15 forward stroke by the operating magnet 642. Wiper 641 normally stands on the tenth bank contact, with the off-normal contacts 643 in open position, as shown. The timer switch TS-1 is a similar mechanism, and is provided 20 for the purpose of freeing the by-pass selector in the case of delayed dialling, as will be pointed out subsequently.

The disclosed system being a ten-thousand line system, the first or thousands selectors are succeeded by penultimate or hundreds selectors, the 25 circuits of the penultimate selector PU-1, Fig. 3, being shown in full. Mechanically the penultimate selectors are somewhat more complicated from a circuit standpoint because they supply 30 talking current to the two lines of an established connection and supply ringing current to the called line.

The arrangement of the penultimate selectors into shelves and sub-groups is the same as described in connection with the first selectors, 35 with two by-pass or directing units assigned to the even-numbered and odd-numbered selectors, respectively, of a shelf-group of ten. The common units for the selector shelf containing the 40 penultimate selectors PU-1 and PU-2 of Fig. 3 are the directors DR-1 and DR-2, Figs. 7 and 8. The term director has been applied to a common controlling unit such as the DR-1, Figs. 7 and 8, because this unit serves, not only as a by-pass selector for the associated penultimate selectors, but also as a register controller to position any connector taken into use by an associated 45 selector.

The director DR-1 includes a by-pass selector 50 BPS-3, Fig. 8, similar mechanically to the mechanism of the by-pass selector BPS-1, Fig. 6. The director DR-1, however, has additional relay equipment and other apparatus to enable it to position any selected connector, as will hereinafter appear.

The connector C1, Fig. 4, is a final selector (or connector) in one of the groups accessible to the 55 selectors, such as PU-1, Fig. 3. This connector is similar mechanically to the selectors, but it differs from a circuit standpoint in that it is caused to return to normal position after each use thereof, with the lower wiper set on the fifty-first set of bank contacts. This different arrangement is employed at the connector because the connector is positioned by a directive control operation instead of by a hunting operation, as in case 60 of the selectors, such as PU-1.

Detailed description

The system having been described generally, a 65 detailed description of the operation of the apparatus shown will now be given. For this purpose it will be assumed that the subscriber at substation A, Fig. 1, desires to converse with the subscriber at substation B, Fig. 4, in which case the

subscriber at substation A removes his receiver and dials the digits in the number assigned to the subscriber at substation B.

Call from substation A to substation B (1166); starting the distributors 80

When the subscriber at substation A removes his receiver to call the subscriber at substation B, whose number it is assumed is 1166, line relay 105 of the line circuit LC energizes over conductors 101 and 103 through the upper and lower contacts of cut-off relay 106. Upon operating, line relay 105 disconnects the private normal conductor 102 from cut-off relay 106 and connects it to ground, thereby guarding the line of substation A from seizure by way of any one of the connectors having access to it. At its middle armature, line relay 105 connects the low-resistance element 104 in parallel with the winding of cut-off relay 106, thereby marking the line of substation A as calling in the banks of the finders, such as F. At its lower armature, relay 105 places ground on start conductor 150, thereby energizing the common start relay 501 to start the distributors D1 and D2 into operation. It will 100 be understood, of course, that both distributors respond by going through substantially similar operations, but the detailed operations of the distributor D1 only will be described.

In the distributor D1, start relay 502 now operates in series with resistance element 509. At its lower armature, start relay 502 prepares a locking circuit for switching relay 504 and closes a polarizing circuit for electropolarized test relay 507; at its upper armature it connects the 110 operating magnet 508 with the test wipers 521 and 526 by way of contacts of the switching relay 504, so as to close a self-interrupting circuit for magnet 508 in case the wipers of the distributor are standing on three contacts associated with a 115 busy link circuit (such as the one shown in Fig. 1); at its inner-upper armature it closes a local stepping circuit for magnet 508 by way of the upper contacts of the group-test relay 503 and the upper contacts of the electro-polarized trunk-test relay 507; and at its inner-lower contacts it connects up the group-test relay 503 to the group-test wiper 527.

As will be explained more fully shortly, operating magnet 508 is now operated in a buzzer-like 125 manner, either because of ground potential being obtained through the link-test wiper 521 or wiper 526, or in a local circuit through contacts of the group-test relay 503, until an idle link circuit is reached having its secondary switch associated with a secondary group in which there is an idle first selector. The link test made by wipers 521 and 526 is a test for an absence of ground potential on the test conductors, such as conductor 154, of an idle link, while the test 130 group test made through wiper 527 is made for ground potential and over group-test conductors, such as 158. The nature and purpose of the group test will now be explained a little more fully.

Since it would be futile to take a finder-secondary link for use and operate the secondary switch thereof in search of an idle first selector when there is no idle first selector accessible to the secondary switch, there is a common-test or group-test conductor, such as conductor 135, extending between Figs. 1 and 2, for each group of secondary switches. This group-test conductor connects to each of the first selectors and associated common apparatus units accessible to the same group of secondary switches. The group- 140 145 150

test conductor 135 is normally grounded by way of each of the five common apparatus units associated with the five sub-groups of first selectors forming the secondary group. It is normally 5 grounded by way of contacts of switching relay 201 and conductor 221 extending to the by-pass selector BPS-1, and the upper contacts of release relay 603, Fig. 6. When the by-pass selector BPS-1 is in use, ground potential is removed at the upper contacts of release relay 603 from conductor 221, thereby ungrounding conductor 135 at one point. If all the by-pass selectors of the same secondary group are in use at one time, it is obvious that ground potential 10 is removed at all points from the group-test conductor 135. Also, when the first selector FS-1 is in use, it breaks one connection between the group-test conductor 135 and conductor 221, so that if all switches in a shelf-sub-group of five 15 are in use, ground potential for that sub-group is thereby removed from the group-test conductor 135, instead of at the by-pass selector.

From the above-discussion, it will be seen that 20 there is idle-indicating ground potential on the group-test conductor 135 at all times, except when there are no trunk lines available in the associated secondary group of twenty-five trunks, at which time there is no ground potential on conductor 135. A similar conductor is provided 25 for each of the other secondary groups.

Seizing an idle finder-secondary link

Referring now again to the distributor D1, Fig. 5, the buzzer-like operation of magnet 508 takes 30 place, either through the local circuit controlled by the contacts of group-test relay 503 or through the link-test wipers 521 and 526, advancing the wipers 521-527 step-by-step in search of an idle link circuit in a secondary group containing one 35 or more idle trunk lines, until an idle link circuit is reached related to a secondary group in which there is at least one outgoing trunk line.

It is to be noted that group-test relay 503 energizes each time it encounters a ground potential 40 on a test contact, indicative of a link associated with a secondary group containing an idle selector, and that relay 503 falls back each time wiper 527 engages a contact associated with a link circuit in a busy secondary group. With relay 503 45 operated, a circuit is prepared for switching relay 504 and the local driving circuit for relay 508 is opened, rendering the further driving of the distributor dependent upon the grounded or ungrounded condition of the test contacts engaged 50 by wipers 521 and 526. It will be assumed that the finder-secondary link composed of the finder F and the secondary switch SS, Fig. 1, is idle and that there is a ground potential on the group-test conductor 135 of the secondary group, indicating that one or more trunks are idle in the 55 secondary group. Under this condition, when the wipers 521-527 land on the contacts associated with conductors 152-158, the driving circuit through wipers 521 and 526 is open on account of conductors 154 and 157 being ungrounded; and group-test relay 503 is operated 60 through wiper 527 and over the local branch 158 of the group-test conductor 135, by way of contacts of relay 115, the flexible spring 116 and the 65 associated jack contact, and a jumper on the distributing frame DF. The driving operation now ceases. Under this condition, a circuit is completed for switching relay 504 through the armature of the operated group-test relay 503 70 and in series with operating magnet 508. Relay

504 thereupon operates in series with magnet 508, but magnet 508 is not operated at this time because of the relatively high resistance of relay 504. Upon operating, relay 504 closes a locking circuit for itself at its inner-lower armature by 80 way of the lower armature of start relay 502; disconnects the link-test and line-test wiper 521 from the circuit of stepping magnet 508 and prepares to extend it by way of contacts of trunk-test relay 507 to the upper winding of line-test relay 506; at its lower armature it disconnects test wiper 526 from the magnet circuit and connects it to ground to guard the link by way of conductor 157 against seizure by the second distributor; at its middle-lower armature it connects trunk-test wiper 524 to trunk test relay 507; and at its inner-upper armature it closes an operating circuit by way of wiper 522 and conductor 156 for operating magnet 134 of the secondary switch SS. 95

Seizing an idle first selector

The wipers 131-133 of the secondary switch SS are now driven by the buzzer-like action of magnet 134 until the wipers come into engagement with an idle trunk line, which trunk line it will be assumed is the one comprising conductors 136-138 and extending to the first selector FS1, Fig. 2. The idle condition of this trunk line is indicated by the application of battery potential to the release-trunk conductor 137 thereof, by way of the flexible test-jack spring 212 associated with the first selector FS1, contacts of switching relay 201, conductor 222, upper armature, normal, of relay 603, flexible test-jack 110 spring 637, contacts of relay 602, and resistance element 638. When wiper 132 encounters the battery potential thus placed on conductor 137, a circuit is closed for the upper winding of trunk-test relay 507 in the distributor D1 by way of wiper 524, conductor 153, contacts of relay 115, a jumper on the distributing frame DF, wiper 132, and conductor 137, to battery over the circuit previously traced through resistance element 638, Fig. 6. 115

It may be pointed out that electro-polarized relay 507 is a Pye polarized relay, the construction and operation of which is explained in the patent to Pye, 1,673,884, granted June 19, 1928. Relay 506 is of the same type as relay 507. This 120 polarized type of test relay is used so as to avoid an operation of the relay in case so-called booster battery is encountered, which has an opposite polarity with respect to ground from the regular exchange battery. With the two windings of 125 relay 507 energized in the same relative direction, relay 507 operates and closes a circuit for the polarizing winding of electro-polarized relay 506 at its inner-lower armature; places ground potential directly on wiper 524 at its lower armature to mark the selected trunk engaged; connects the upper winding of relay 506 at its inner-upper contacts to wiper 521, by way of the upper armature of the operated switching relay 504, preparatory to testing for the calling line; at its 140 upper armature it disconnects ground potential from the operating magnet of the secondary switch SS and connects it by way of wiper 523 and conductor 152 to the operating magnet 114 of the finder F. By this operation, the secondary switch SS is stopped, and the finder F is 145 started into operation to find the calling line.

It is to be noted that relay 507 removes ground at its middle-upper armature from the armature of the group-test relay 503, thereby finally 150

terminating the group test. This ground potential is allowed to remain on the upper armature of relay 503 after switching relay 504 has energized and locked itself at its inner-lower armature so that in case all the trunk lines in the selected secondary group become busy before an idle trunk in the group has been found, as indicated by the energized or non-energized condition of relay 507, relay 503 falls back and starts 10 the link testing operation again, as it closes a direct circuit again for magnet 508 under the assumed condition and thereby short-circuits and deenergizes relay 504. With relay 507 now energized, however, the ground potential is re- 15 moved from the armature of group-test relay 503 as above pointed out, and the group-test is thereby effectively terminated.

Finding the calling line

20 The finder F now operates responsive to the buzzer-like action of magnet 114 until wipers 108-110 reach the contacts assigned to the line of substation A, whereupon the upper winding of 25 the line-test relay 506 in the distributor D1 is energized in series with resistance element 104 in the line circuit LC, through contacts of the energized line relay 105 and contacts of the non-energized cut-off relay 106, wiper 109, conductor 30 154, wiper 521, and contacts of the energized relays 504 and 507. Upon operating, relay 506 opens the circuit of operating magnet 114 at its upper armature, thereby terminating the advance of the finder F; it closes a shunt around the 35 winding of start relay 502 at its lower armature; and at its inner-lower armature it grounds the switching-relay wiper 525, thereby closing a circuit over conductor 155 for switching relay 115 of the illustrated finder-secondary link. Switching relay 115 now operates and joins the wipers of the finder F with the wipers of the secondary switch SS. Relay 115 also opens the group-test circuit at its lower armature, and it prepares a locking circuit for itself at its inner-lower contacts, thereby extending its initial energizing ground potential by way of wiper 109 to cut-off relay 106. When cut-off relay 106 operates, it opens the associated branch of the start circuit at its middle-lower armature; disconnects resistance element 104 at its inner-lower armature, and at its upper and lower armatures it disconnects the line relay circuit from conductors 101 and 103, whereupon line relay 105 falls back and joins test conductor 102 to the cut-off relay again.

55 In the distributor D1, group-test relay 503 restores when the group-test circuit is opened at the lower contacts of relay 115. Moreover, start relay 502 restores following the elapse of a short interval after its winding is shunted at the lower contacts of the line-test relay 506. When it falls back, relay 502 opens the circuit of switching relay 504 and test relay 507 at its lower armature, whereupon these relays restore, and relay 507 opens the circuit of relay 506, causing relay 506 to restore. When relay 506 restores, the distributor is in normal condition in readiness to be operated again. Ordinarily, the common start relay 501 has restored by the time relay 506 restores, but in case another call is waiting, relay 501 remains operated and relay 502 immediately reoperates to start the distributor D1 into operation for the next call.

With the deenergization of the common start relay 501, the distributor D2 stops operating and 75 clears out.

Preparing the first by-pass selector for operation

With switching relay 115, Fig. 1, and cut-off relay 106, both energized, the calling line is now freed of attachments and extended through to the first selector FS1 by way of conductors 136 and 138. Conductors 136 and 138 are connected through contacts of switching relay 201 to the common-line conductors 224 and 225, with the lower winding of the connecting relay 202 of the first selector in series with conductor 225. Conductors 224 and 225 are connected through contacts of switching relay 608 to line relay 606 in the by-pass selector. The upper winding of line relay 606 is connected directly to the ungrounded pole of the exchange battery, while the lower winding of line relay 606 is connected with the grounded pole of the exchange battery by way of contacts of relay 601 and the dial-tone conductor 636. Accordingly, line relay 606 of the by-pass selector BPS-1 now operates over the calling line, and the calling subscriber hears the dial tone impressed on conductor 636, notifying him that he may now manipulate his calling device in accordance with the digits of the desired number.

It is to be noted that the winding of release relay 603 is normally shunted through the contacts controlled by the armature of line relay 606. When relay 606 operates, it closes a circuit for relay 603 through resistance 639, and opens the above-mentioned shunt path. Line relay 606 also disconnects the operating magnet 642 of the register switch RS-1. Relay 603 now operates in series with resistance element 639 and closes a self-locking circuit at its inner-upper armature; it connects the common time-impulse lead 630 to the operating magnet 634 of the timing switch TS-1 at its lower armature, and opens a point in the self-restoring circuit of the operating magnet 634 at its inner-lower armature; at its middle-upper armature it removes ground potential from the common-test conductor 221 and connects ground potential to the local locking conductor 629; and at its upper armature it disconnects common release trunk conductor 222 from battery by way of resistance element 638 and connects it to ground, thereby providing a holding circuit through the contacts of switching relay 201 of the first selector FS-1 and jack spring 212 for relays 115 and 106, Fig. 1. This circuit, it will be understood, is established before the slow-releasing start relay 502 of the distributor D1 falls back as before described.

In the first selector FS1, connecting relay 202, the lower winding of which is connected in series with the common line conductor 225, energizes in series with line relay 606 of the by-pass selector BPS-1. At its inner-upper armature, line relay 202 closes a locking circuit for its upper winding over the grounded common release trunk conductor 222; it bypasses its lower winding at its inner-lower contacts; it prepares a trunk-test circuit at its upper armature; and at its middle-lower and lower armatures it prepares circuits for operating magnet 203 and switching relay 201.

Dialling the first digit (1)

When the subscriber at substation A manipulates the dial of his calling device in accordance with the first digit in the desired number, a corresponding series of interruptions is produced in the calling line. Each time the circuit over the calling line is interrupted, line relay 606 in the by-pass selector BPS-1 restores. Each time it

145

150

restores, line relay 606 closes a circuit for operating magnet 642, by reconnecting the operating magnet to the operating circuit at its lower armature and by replacing the shunt around release relay 603 at the normally closed contacts controlled by its inner armature. Series relay 605 operates in parallel with resistance element 639 and operating magnet 642 when the first impulse is delivered to magnet 542, and it remains operated throughout the series of impulses because it is a slow-acting relay, and also because of the shunt circuit for it through the resistance element 639. Release relay 603 remains operated throughout the series of impulses, as it is rendered slow-releasing by the shunt circuit being placed around it at the contacts controlled by the inner armature of line relay 606. By the operation of magnet 642, wiper 641 of the register switch RS-1 is advanced step-by-step until it comes to rest on the bank contact corresponding to the digit dialled.

Group selection at the by-pass selector

When series relay 605 operates responsive to the first impulse, it locks itself at its lower armature in multiple with resistance element 639 and independent of the normally closed contacts controlled by armature 622; opens points in the test circuit of relays 608 and 609 at its inner-lower and middle-lower armatures; prepares a starting circuit for operating magnet 610 at its upper armature; and at its inner-upper armature it closes a circuit from conductor 629 (grounded at the middle-upper armature of release relay 603) for release-control relay 601. Relay 601 now operates and makes a multiple ground connection to conductor 222 at its upper armature; substitutes direct ground potential for ground potential by way of the dial-tone conductor 636 at armature 621, thereby terminating the application of dial tone current; it connects resistance element 640 in shunt of release relay 603 and opens the initial circuit of series relay 605 at armature 622, for a purpose to be hereinafter explained; opens a point in the circuit of relay 602 at its inner-upper armature; opens a point in the restoring circuit of the register RS-1 at its lower armature; at its inner-lower armature prepare a special control circuit for the lower winding of relay 602 in the event of an overflow condition in the selected trunk group; and at armature 623 it completes a circuit from the grounded conductor 629 by way of the operated upper armature of series relay 605, contacts of relays 604, 608, and 609, and the associated self-interrupting contacts for operating magnet 610.

Operating magnet 610 now starts to operate in a buzzer-like manner to rotate the wipers 611-620 of the by-pass selector in search of the trunk group indicated by the assumed position of wiper 641 of the register RS-1. It will be understood, of course, that the group-hunting operation of the by-pass selector is produced concurrently with the stepping of the register RS-1, as relays 605 and 601 energize successively responsive to the first impulse to start the operation of magnet 610. Under ordinary conditions, the wipers 611 to 620 advance over the contact groups at about the same rate that the wiper 641 of the register RS-1 advances from one contact to the next, and the group-test relay 604 may operate and restore a number of times during the receipt of the digit and the positioning of the by-pass selector. At any rate, when the wipers 611 to 620 advance to their first off-normal position (they

normally stand on the fifty-first set of bank contacts) wiper 620 places ground on the group of contacts in its bank corresponding to the first trunk group, thereby closing a circuit for the group-test relay 604 through wiper 641 on the first contact, to which it was advanced responsive to the first impulse. When relay 604 operates, it opens the circuit of magnet 610 at its upper armature to halt the group-hunting operation. Then, when wiper 641 advances to the second contact, responsive to the second received impulse, relay 604 deenergizes and closes the driving circuit of magnet 610 again, which driving circuit remains closed until wiper 620 again catches up with wiper 641 and brings about the reoperation of the group-test relay 604.

In the present assumed example, the received digit is the digit 1, represented by a single impulse. Therefore, wiper 641 advances to the first contact in its bank and remains there, causing the group-hunting operation of the by-pass selector to be terminated with the wipers 611-620 in association with the trunk lines in the first trunk group.

With line relay 606 in an energized condition at the end of the dialled digit, the impulse-series relay 605 shortly falls back to mark the end of the digit. Relay 605 is adjusted so as not to hold up with the current flow through it in multiple with resistance element 639, with the two connected in series with relay 603. However, with the current flow through relay 605 and resistance element 639 increased by the additional current flowing through resistance element 640, now connected in shunt of the winding of relay 603 through armature 622 of the operated relay 603 and resting contacts of the group-test relay 604 (assuming that relay 604 has not yet operated), relay 605 remains operated as long as resistance element 640 remains connected in shunt of relay 603. By this arrangement, relay 605 does not fall back to mark the end of the digit and thereby start the trunk hunting operation until relay 604 operates to indicate that the group indexed by the called digit has been located by the by-pass selector. The value of resistance element 640 is so related to the windings of relays 603 and 605 that the current flow through relay 605 with resistance element 640 in circuit is just sufficient to hold the relay operated. Therefore, when relay 604 operates (in the event that the operation of relay 604 is delayed beyond the time when relay 605 would normally fall back), relay 605 restores almost immediately, thereby introducing a minimum delay between the end of the digit and the starting of the trunk-hunting operation.

Trunk hunting

When series relay 605 restores at the end of the digit as above pointed out, it opens the initial circuit of release-control relay 601 at its inner-upper armature, leaving relay 601 locked up at its inner-upper armature to conductor 629 by way of contacts of relay 607. At its lower armature relay 605 disconnects itself and magnet 642 from the operating circuit (relay 601 being in operated condition); at its upper armature it extends ground potential from conductor 629 by way of the operated armature 623 to the operated inner-lower armature of the group-test relay 604; and at its inner-lower and middle-lower armatures it extends the ground potential from the now-grounded working contact of the inner-lower armature of the operated relay 604 to the test windings of the switching and wiper-switching

relays 608 and 609, thereby enabling these relays to test for idle trunk lines in the selected group.

At the same time that relay 605 extends ground potential at its upper armature to the inner-lower armature of the group test relay 604, relay 604 being operated the ground potential is extended through the upper armature of relay 604 and the contacts of switching relays 608 and 609 to the operating magnet 610. Magnet 610 now drives the wipers in search of an idle trunk.

For the purpose of halving the number of hunting steps required to be taken by the wipers 611-620 of the by-pass selector, the wipers 611, 612, and 614-619 are divided into two groups, with the directing wiper 620 and the restoring wiper 613 common to both groups. The wipers 611, 612, 614, and 615 constitute the first group, while wipers 616-619 constitute the second group. Each group contains a pair of line wipers, line wipers 611 and 612 for example; a trunk test wiper, wiper 614 for example, and a position-test wiper, wiper 615 for example. By this arrangement, each off-normal position of the by-pass selector corresponds to two trunks. Now, keeping in mind that the driving circuit for operating magnet 610 is now closed through contacts of relays 608 and 609 and that the test circuits for relays 608 and 609 are now closed at the contacts of series relay 605 and through test wipers 614 and 618, respectively, it will be understood that one (or both) of the relays 608 and 609 operates in case one (or both) of the trunk lines now engaged by the two wiper sets of the by-pass selector is idle, while if both of the trunk lines are engaged neither relay 608 nor relay 609 operates, and the wipers 611-620 are driven step-by-step by the operation of magnet 610 until a pair of trunk lines is reached, at least one of which is idle.

Trunk seizure

It will be assumed that the first pair of trunk lines reached in which at least one trunk line is idle is the pair comprising conductors 231-234 and 241-244. It will be assumed further that the trunk line comprising conductors 241-244 is in use at this time, and that it is the trunk line comprising conductors 231-234 which is idle. Under this condition, there is no idle-indicating battery potential on conductor 243, and so wiper-switching relay 609 does not operate. Since the trunk comprising conductors 231-234 is idle, there is an idle-indicating battery potential on conductor 233, causing relay 608 to operate through contacts of relay 609 and by way of wiper 614. The idle indicating potential for operating relay 608 is obtained over conductor 233 by way of test-jack spring 309 of the penultimate selector PU-1, contacts of relays 303 and 308, the common release-trunk conductor 346 associated with the director DR-1, Figs. 7 and 8, inner-lower armature and resting contact of release relay 801, inner-lower armature and resting contact of relay 707, test-jack spring 712, and resistance element 713.

Upon operating, relay 608 opens the driving circuit of operating magnet 610 at armature 632, thereby terminating the trunk-hunting movement; by-passes its test winding at its inner-upper armature by connecting the grounded conductor 629 through contacts of relay 609 to test wiper 614, thereby rendering the penultimate selector PU-1 busy, and at the same time rendering the remaining idle penultimate selectors associated with the director DR-1 busy by way of

the common release-trunk conductor 346, opens a point in the test circuit of relay 609 to prevent relay 609 from operating subsequently and thereby interfering with the connection established by relay 608 through armatures 655 and 656; at 180 armatures 651 and 652 it switches the incoming talking conductors 224 and 225 from line relay 606, by way of armatures 655 and 656 to wipers 611 and 612, now standing on conductors 231 and 234 leading to the penultimate selector PU-1, 185 Figs. 3. By this operation, the penultimate selector is taken for use, and the director DR-1, Figs. 7 and 8, is now available to receive the next digit in the desired number, by way of wipers 611 and 612 of the by-pass selector BPS-1, Fig. 6. 190

In the meantime, line relay 606 falls back responsive to being disconnected at armatures 651 and 652. The operating magnet 642 of the register RS-1 does not operate again at this time because relay 601 is operated and locked at its 195 inner-upper armature through the contacts of position-test relay 607. At the normally closed contacts controlled by its inner armature, relay 606 places a shunt around release relay 603, causing release relay 603 to restore. The restoration 100 of relay 603 at this time does not cause any harm to result, as release-trunk conductor 233 has by now become grounded by the director DR-1 (as will be explained later). With relay 608 operated and relay 609 non-operated, as is now the case, 105 conductor 629 receives ground potential from release-trunk conductor 233, maintaining relays 608 and 601 operated. Relay 601 maintains the common release-trunk conductor 222 grounded at its upper armature, thereby maintaining the 110 by-pass selector BPS-1 and the remaining idle associated conversational switches guarded for the time being.

Positioning the first selector FS-1

Relay 608 also closes a circuit from ground, on the grounded conductor 629 and through contacts of the position-test relay 607, over conductor 226 for operating magnet 203 of the first selector FS-1, by way of contacts of the connecting relay 202. The operating magnet 203 of the first selector FS-1 now starts to operate in a buzzer-like manner to advance the wipers 204-211 in search of the trunk line selected by the by-pass selector BPS-1. 120

The wipers 204-211 of the first selector FS-1 continue to be operated by magnet 203 until wipers 204-207 arrive on the conductors 231-234, constituting the trunk line which has been seized by way of the wipers of the by-pass selector BPS-1. When the wipers 204-207 arrive on these conductors, wiper 205 extends a ground potential (obtained through resistance element 212 and the upper contacts of connecting relay 202) over conductor 232 to the position-test relay 607 by way of wiper 615 and contacts of the non-operated wiper-switching relay 609. The position-test relay 607 immediately operates and opens the driving circuit of operating magnet 203 of first selector FS-1, thereby terminating the movement of the wipers. At the same time, relay 607 connects the grounded conductor 629 to the switching conductor 223, thereby closing a circuit through contacts of connecting relay 202 for switching relay 201 of the first selector FS-1. Switching relay 201 now operates and connects the incoming release-trunk conductor 137 with test wiper 206, at the same time locking itself to the release-trunk conductor; it disconnects the incoming release trunk conductor 137 from the 130 135 140 145 150

common release-trunk conductor 222 at its inner-upper armature; it disconnects one branch of the group-test conductor 135 from the common test conductor 221 of the by-pass selector BPS-1 and 5 connects it to the associated supervisory lamp 214; and it connects the incoming conductors 136 and 138 directly to the wipers 204 and 207, at the same time disconnecting the incoming talking conductors from the corresponding conductors 124 and 225 leading to the by-pass selector. The 10 connection to the trunk comprising conductors 231, 233, and 234 and extending to the penultimate selector PU-1 is thus changed over to include the conversational switch FS-1 instead of the 15 by-pass switch BPS-1.

Restoring the by-pass selector BPS-1

In the by-pass selector BPS-1, relay 601 now 20 restores because its circuit was opened upon the energization of relay 607, along with the opening of the driving circuit of the first selector FS-1. When it restores, relay 601 closes the restoring 25 circuit of the register RS-1 at its lower armature and by way of off-normal contacts 643. The register RS-1 is now operated in a step-by-step manner by the buzzer-like action of operating magnet 642 until it arrives in its normal position, whereupon the operation ceases because off-normal contacts 643 separate. Relay 601 also 30 moves ground potential from conductor 222 at its upper armature, whereupon the remaining idle conversational switches associated with the by-pass selector are rendered idle, and connecting relay 202 of the first selector FS-1 is unlocked and 35 restores. Moreover, relay 601 at its inner-lower armature connects restoring wiper 613 to operating magnet 610. Operating magnet 610 now 40 operates in a buzzer-like manner to drive the wipers 611-620 until they reach normal condition. As soon as the wipers start to move, ground potential received by wiper 614 over conductor 233 45 is disconnected, permitting the operated relay 608 to restore. Relay 602 is operated from wiper 613 through armature 624, normal, and disconnects magnet 642 from relay 605, preventing relay 605 from reoperating during the restoration period and reoperating release-control relay. The group-test and position test relays 604 and 607 50 are restored responsive to the movement of the wipers.

Preparing the director DR-1 for operation

Responsive to the seizure of the penultimate selector PU-1, which seizure is first accomplished 55 by the by-pass selector as hereinbefore explained and then taken over by the conversational switch FS-1, the calling loop extended to conductors 231 and 234 causes connecting relay 307 in the penultimate selector to be energized in series 60 with line relay 711 in the director DR-1. It is to be noted that line conductor 234 is grounded by way of the lower armature of relay 303, and that relay 307 has its upper winding connected between the common negative line conductor 345 65 and the incoming talking conductor 231, by way of the upper armature of relay 303.

When connecting relay 307 operates in series 70 with line relay 711, it locks itself to the common release trunk conductor 346 at its inner-lower armature; it places a shunt around its upper winding at its inner-upper armature; and at its remaining contacts it prepares the penultimate selector PU-1 for operation in conjunction with the director DR-1.

75 In the director, when line relay 711 energizes,

it opens a point in the magnet operating circuit at its upper armature, and at its inner armature it applies ground potential to conductor 720 and removes a shunt from around the winding of release relay 801, whereupon relay 801 operates in series with series relay 802. Series relay 802 does not respond at this time because of the relatively high resistance of release relay 801. Upon operating, relay 801 places an additional ground potential on conductor 720 at its upper armature, thereby closing a locking circuit for itself; it places ground potential on the common-release trunk conductor 346 at its inner-lower armature, thereby closing a holding circuit for the previously established portion of the connection before the previously explained deenergization of relay 601 of the by-pass selector BPS-1 has occurred and removed ground potential from release-trunk conductor 222; and at its remaining armatures, relay 801 completes the preparation of the director DR-1 for operation.

Dialling the hundreds digit (1)

When the second digit (the hundreds digit) of the number is dialled, line relay 711 of the director DR-1 falls back a corresponding number of times. Each time it restores, line relay 711 replaces the shunt around the winding of release relay 801 at the contacts controlled by its inner armature, and at its upper armature it completes a circuit for operating magnet 812 of the register switch RS-2, from the grounded conductor 720 by way of armatures 730 and 732. By the operation of magnet 812, wiper 810 is advanced step-by-step in a counter-clockwise direction to mark the contact corresponding to the value of the received digit.

Series relay 802 responds to the first shunting of release relay 801, when the first impulse is received, and it remains operated throughout the series of impulses. Upon operating, series relay 802 opens points in the test circuits of relays 807 and 808 at its inner-lower and middle-lower armatures; it prepares a driving circuit for operating-magnet 810 at its inner-upper armature; and at its upper armature it connects resistance element 809 in shunt of release relay 801 by way of contacts of the group-test relay 804, so as to maintain the series relay operated until the group-test has been completed, as explained more fully in connection with series relay 605 of the by-pass selector BPS-1, Fig. 6.

Group selection at the penultimate by-pass selector

When the wiper 813 of the register switch RS-2 is advanced responsive to the first impulse, it closes a circuit for the group-test relay 804 through wiper 830 in its normal position on its fifty-first associated contact, whereupon relay 804 operates and opens a point in the driving circuit at its inner-upper armature, while at its lower armature it closes a circuit from the grounded conductor 720 for the hunting-control relay 709. Relay 709, thereupon operates and locks itself to conductor 720 at armature 741, by way of armature 735 of relay 710; it prepares a test circuit for relays 807 and 808 at its lower armature; and at armature 742 it closes a point in the driving circuit of magnet 810, so as to start the group-hunting operation as soon as the group-test relay 804 falls back responsive to the second step of wiper 813 of the register switch RS-2.

When wiper 813 is advanced through its sec-

80

145

150

ond step and comes upon its second contact, group-test relay 804 deenergizes and closes the driving circuit, which circuit extends from the grounded conductor 720, through armature 742 of the operated relay 709, inner-upper armature of the operated series relay 802, inner-upper armature of relay 804, armature 834, contacts of test relay 808, and the self-interrupting contacts of magnet 810, to the winding of the said magnet. This circuit remains closed until the wipers 821—830 have been driven in a clockwise direction until wiper 830 overtakes wiper 813 of the advancing register RS—2, whereupon relay 804 is again operated to break the driving circuit at its inner-upper armature. 5

When the impulse series has ended, and the wipers of the by-pass selector BPS—3 have been rotated to the position corresponding to the one assumed by wiper 813 of the register RS—2, and group-test relay 804 has become energized to terminate the group-hunting movement, series relay 802 restores because it is unable to remain operated for more than a short interval of time in series with release relay 801 when release relay 801 is not shunted by resistance element 809. 10

When it restores, series relay 802 closes points in the test circuits of the lower windings of electro-polarized relays 807 and 808 at its inner-lower and middle-lower armatures, and at its inner-upper armature it completes the driving circuit for magnet 810 through the operated inner-lower armature of group-test relay 804, whereupon the trunk-hunting operation starts. 15

35 Trunk hunting

In the assumed call, the digit received at the register RS—2 is the digit 1, in which case the wipers 821—830 have not been rotated at all as a result of the digit being received as they are normally in position to start rotating over the first group of trunk lines and need not move over this trunk group during the dialling of a digit unless this digit has a value greater than one. Therefore, the wipers are now driven out of their normal position on the fifty first set of bank contacts and are rotated in a clockwise direction until test wiper 823, associated with relay 808, encounters an idle-indicating battery potential on the release-trunk conductor on an idle trunk line. 40

Trunk seizure

55 In the present case, it will be assumed that the first trunk line found to be idle is the one comprising conductors 329—332 and the one comprising conductors 333—336, simultaneously encountered by wipers 826—829, is in use. Under these conditions, the wiper-switching relay 808 is not operated, but switching relay 807 is operated because the upper terminal of its lower winding is supplied with ground potential through the lower armature of the operated relay 709 and through the inner-lower armature of series relay 802; the lower terminal of the lower winding of relay 807 is connected through contacts of wiper-switching relay 808 to the test wiper 823. The test circuit over conductor 331 is complete to battery by way of test-jack spring 405 of the connector C—1, Fig. 4, and resistance element 406. Upon operating, relay 807 by-passes its lower winding so as to place a guarding ground potential on the release-trunk conductor of the seized trunk; opens a point in the test circuit of relay 808 and its lower armature so that relay 808 cannot now operate in case the alternate trunk line of the pair becomes idle; at its inner-upper armature it interrupts the driving circuit of magnet 810, thereby stopping the wipers on the selected trunk; it opens an additional point in the driving circuit and prepares a circuit for transfer and connector-start relay 710 at armature 833; and at its upper armature it extends ground potential from the grounded conductor 720 through the contacts of the position-test relay 806 and over conductor 347 to the operating magnet 310 of the penultimate selector PU—1, by way of contacts of the connecting relay 307. 5

Positioning the penultimate selector PU—1

The operating magnet 310 of the penultimate selector PU—1 now starts to operate in a buzzer-like manner to drive the wipers 321—328 in a clockwise direction until contact is made with the trunk line which has been selected by the by-pass selector BPS—3 of the director DR—1, Figs. 7 and 8. 95

When the wipers 321—324 arrive on the set of bank contacts in which the conductors 329—332 terminate, wiper 322 extends a ground potential (obtained through contacts of connecting relay 307) over conductor 330 and by way of wiper 822 and the inner-upper armature of relay 808 to the position-test relay 806. Position-test relay 806 thereupon operates and interrupts the driving circuit of magnet 310, stopping the wipers of penultimate selector PU—1 on the previously selected trunk line. 100

Dialling the tens digit (6)

When the tens digit is dialled, the digit 6 in the assumed example, line relay 711 of the director DR—1 is deenergized momentarily six times. Each time it restores, line relay 711 closes the previously traced circuit from ground on conductor 720 by way of armatures 730 and 732 for the operating magnet 812 of the register RS—2, thereby causing the register to take six steps from the first off-normal contact. This contact, it will be recalled, is now marked with ground potential because wiper 830 of the by-pass selector BPS—3 is now standing on the group of multiple contacts corresponding to the digit dialled. In this case, since the digit one was the digit dialled, then wiper 830 is now standing on one of its first five contacts, the third contact to be exact, because the third trunk in this group is the idle trunk selected. The dialling of this digit, it will be understood, may begin while the penultimate selector PU—1 is searching for the position assumed by the by-pass selector BPS—3. 115

When the first impulse is delivered to operating magnet 812, series relay 802 is operated, as before, through the contacts controlled by the inner armature of relay 711, and it remains operated throughout the series of impulses. It is to be noted that resistance element 809 is not shunted around relay 801 at this time as the shunt path through this resistance element is open at the upper armature of the operated relay 807. 120

As soon as wiper 813 takes its first step, responsive to the first impulse in the tens digit, the circuit of the group-test relay 804 is opened, whereupon relay 804 restores, thereby closing a circuit through the operated armature 834 for 130

the upper winding of test-control relay 805, by way of contacts of relay 803. This circuit includes the inner-upper armature of the operated series relay 802, armature 742 of the operated 5 relay 709, and the grounded conductor 720. When relay 805 operates, it closes a locking circuit for itself at its upper armature through contacts of relays 803 and 801; it opens a point in a subsequently used energizing circuit for 10 the already energized-and-locked relay 709 at its lower armature; and at its inner-lower armature it disconnects the now ungrounded wiper 813 from the deenergized relay 804 and prepares a circuit for its own lower winding in series with 15 relay 803.

With relay 804 now restored, and with switching relay 807 operated, when series relay 802 restores at the end of the tens digit, it closes a circuit through the middle armature of relay 20 804 and by way of the operated armature 833 for the transfer and connector-start relay 710. When relay 710 operates, it opens the locking circuit of hunting-control and tens-cut-off relay 709 at armature 735, whereupon relay 709 25 stores and operates relay 704 at armature 741; prepares a circuit for relay 703 at its lower armature; and at armature 730 and 729 it disconnects operating magnet 812 of the register switch RS-2 from the operating circuit and 30 substitutes operating magnet 721 of the register RS-3, preparatory to the units digit being received by the register RS-3.

Dialling the units digit (6)

35 When the units digit is dialled, the digit 6 in the assumed example, line relay 711 restores six times. Each time it does so, it closes a circuit from the grounded conductor 720 through the 40 operated armature 729 and armature 731 for operating magnet 721. Magnet 721 advances wiper 723 six steps in a clockwise direction.

Series relay 802 is operated again during the units digit and remains operated until the end 45 of the digit. Upon operating, relay 802 closes a circuit at its lower armature from ground by way of the grounded conductor 720, and the lower armature of the operated relay 710, for relay 703, by way of the inner-upper contacts of relay 50 702. When relay 703 of the counting pair comprising relays 702 and 703 operates at its lower armature and its upper armature, it closes two locking circuits for itself. The first locking circuit is from the grounded conductor 720 by way 55 of armature 741 of the now-deenergized relay 709, and armature 733; and the second locking circuit is from ground by way of the grounded release-trunk conductor 346 and the winding of relay 702. Relay 702 does not operate at this 60 time because it is supplied with ground potential at both terminals.

When relay 802 restores, at the end of the units digit, it leaves relays 703 and 710 operated and locked to conductors 346 and 720.

65 *Group selection at the connector C-1*

When the combined transfer and connector-start relay 710 operates responsive to relay 802 70 restoring at the end of the impulses constituting the tens digit, in addition to transferring the operating circuit from the register RS-2 to the register RS-3 at armatures 730 and 729, relay 710 connects the revertive pulse relay 708 to wiper 75 821 of the by-pass selector at its upper arma-

ture, by way of the upper armatures of relays 709 and 707, and at armature 737 it connects ground potential (from the grounded conductor 720 by way of the resting contacts of armature 742) to wiper 824 of the by-pass selector BPS-3. 80 As a result, the revertive pulse relay 708 is now connected by way of wiper 821 to conductor 329 leading to the connector C-1, and ground potential is now placed on conductor 332 by way of the associated wiper 824. At the same time, relay 710 prepares a circuit at armature 736 for the lower winding of the tens-test relay 803 in series with the lower winding of the energized test-control relay 805, while at armature 730 it closes a control circuit for operating-magnet 812 85 of the register RS-2, which circuit includes armatures 732 and 730, inner-upper armature of relay 709, normally closed contacts controlled by the inner armature of the revertive-pulse relay 708, inner-upper armature of relay 710, and the inner-upper armature of the release-control relay 707. As a result, operating magnet 812 now energizes and advances the wiper 813 one step 90 pursuant to the revertive control of the connector C-1, under the control of the revertive-pulse 100 relay 708.

In the connector C-1, start relay 403, the lower winding of which is connected to incoming conductor 332 by way of contacts controlled by armature 421, and the lower armature of relay 401, 105 operates in response to the ground potential placed on the incoming conductor 332, as above explained. Upon operating, relay 403 at its upper armature locks itself to the grounded release-trunk conductor 331 by way of the upper 110 winding of relay 402, but relay 402 does not operate for the time being, because it is supplied with ground potential at both terminals; it connects the incoming conductor 329 through its own upper winding to wipers 410 and 414 at its 115 inner-upper armature, at the same time disconnecting wipers 410 and 414 from the lower winding of relay 401; and at its lower armature it opens a point in the restoring circuit of magnet 404 and closes a local self-interrupting circuit 120 for magnet 404 through the lower armature of the non-operated relay 402. Magnet 404 now starts to operate in a buzzer-like manner to advance the wipers 408-415 in a clockwise direction over the associated contact bank. It is to 125 be noted that wipers 412-415 are advanced off the last contact set in the associated bank upon the first step, while wipers 408-411 are advanced onto the first set of associated bank contacts on the same step of the switch. The advance of 130 the switch continues without any particular immediate effect until the fifth step of the wipers occurs, whereupon wiper 410, encounters the grounded fifth contact in the first encountered line-group. When this happens, a circuit is 135 closed from ground by way of wiper 410, the upper winding of the operated relay 403, the inner-upper armature of the same relay, through the contacts of relay 401, and over conductor 329, for the revertive-pulse relay 708 in the director 140 DR-1. This circuit, it will be recalled, includes the upper armature of the release-control relay 707, and the upper armatures of relays 710 and 709. When relay 708 operates, it opens the circuit of operating magnet 812 at the normally 145 closed contacts controlled by its inner armature, whereupon magnet 812 restores preparatory to advancing the wiper 813 an additional step.

The correspondence between the tens groups or lines or contacts (considered in consecutive 150

order from normal position), the number of revertive impulses sent back in reaching the groups, and the tens digits, is as follows:

	Consecutive groups	Revertive impulses	Tens digits
10	1	10	1
	2	1	0
	3	2	9
	4	3	8
	5	4	7
	6	5	6
	7	6	5
	8	7	4
	9	8	3
	10	9	2

15 In any case, the number of revertive impulses transmitted back to the revertive-pulse relay 708 is the complement of the tens digit, with respect to eleven. In other words, the number of impulses 20 in the tens digit added to the number of revertive impulses always equals eleven.

The contacts accessible to wipers 410 and 414 are divided into groups of ten, conductor 420 being connected to the first four contacts in each 25 group of ten, while ground potential is connected to the last six contacts in each group. As a result, a revertive pulse is initiated each time wiper 410 arrives on the fifth contact in a group and is terminated when wiper 410 leaves the tenth 30 contact in the group. The particular number of contacts in a group to which conductor 420 and ground potential are connected is in some measure arbitrary, but the assignment of four and six has been found by experiment to be quite 35 satisfactory.

When wiper 410 leaves the final contact in the first group, it engages an ungrounded contact in the second group (connected to conductor 420), thereby opening the circuit through the upper 40 winding of relay 403 for revertive-impulse relay 708 in the director DR-1. Relay 708 thereupon restores and again operates magnet 812 for the second control step.

As this operation continues, wiper 813 is advanced one additional step each time wiper 410 passes off the last grounded contact in a new 45 group. Keeping in mind that the tens digit dialled is the digit 6 and that wiper 813, therefore, has been advanced six steps beyond the 50 position marked by wiper 830 consequent to the trunk hunting operation of the by-pass selector BPS-3, it will be seen that the wiper 813 has again arrived on the marked contact when four additional, control impulses have been imparted to 55 magnet 812. Magnet 812 receives one impulse, it will be recalled, before the first revertive impulse to relay 708, and an additional impulse at the end of each revertive impulse, when relay 708 restores.

60 The fourth control impulse is delivered to magnet 812 just as wiper 410 of the connector terminates the third revertive impulse, and enters the fourth consecutive group. At this time, a circuit is closed through wipers 830 and 813 65 in series for the lower winding of the operated test-control relay 805, in series with the lower winding of the tens-test relay 803, by way of armature 736. Relay 803 is thereupon operated to open the locking circuit of the upper winding 70 of relay 805 at its inner-upper armature and close a locking circuit for itself. Relay 805 remains operated for the time being through its lower winding. Relay 803 also prepares a circuit at its lower armature for reoperating relay 709 75 as the tens-cut-off relay, while at the same time

it prepares a shunt circuit for relay 709 at its upper armature.

Now, when wiper 410 engages the first ground-ed contact in the fourth associated group, revertive-pulse relay 708 is again operated to again 80 open the circuit of operating magnet 812. Then, when wipers 408-411 leave the last contact set in the fourth group, and wipers 412-415 arrive on the first contact in the fifth tens group, the circuit of revertive pulse 708 is opened again, 85 and relay 708 restores and again reoperates magnet 812, whereupon wiper 813 is stepped off the contact marked by the wiper 830, opening the circuit through the lower windings of relays 803 and 805. Relay 803 remains operated and locked, 90 but relay 805 restores because its locking circuit has been opened by relay 803. When it restores, relay 805 closes at its lower armature a circuit through the lower armature of the operated relay 803 for relay 709, but relay 709 does not 95 now operate because it is shunted by ground potential supplied to the upper terminal of the associated current supply resistance element, in parallel with the now-operated magnet 812, through the upper contacts of tens-test relay 803. 100

When the revertive-pulse relay 708 next operates, responsive to wiper 410 of the connector C-1 encountering ground potential in the fifth consecutive contact group, it opens the circuit of operating magnet 812, allowing this magnet to 105 deenergize, at the same time removing the shunt from around the winding of relay 709, which shunt was previously established through the normally closed contacts controlled by the inner armature of relay 708, upper armature and resting contact of relay 709, and the upper armature of relay 803. When the shunt is removed from around its winding, relay 709 operates through the lower armatures of relays 803 and 805. Upon operating, relay 709 at its upper armature opens 110 a point in the circuit of relay 708, leaving relay 708 operated for the time being through its own upper armature and the upper armature of relay 702; it removes ground potential from the positive wiper 824 of the by-pass selector BPS-3 at 115 armature 742; and at armature 741 it opens the main branch of the upper locking circuit of relay 703, leaving this locking circuit closed through an armature of series relay 704.

In the connector C-1, when ground potential 120 is removed from the incoming conductor 332 at armature 742 of relay 709, Fig. 7, the upper winding of 402 in the connector C-1 is no longer shunted, and relay 402 operates in series with the lower winding of relay 403, from ground potential 125 encountered on release-trunk conductor 331 by way of the upper armature of relay 403. When relay 402 operates, it disconnects the lower terminal of its upper winding from relay 403 and closes a locking circuit for its two windings in 130 series, which locking circuit includes the upper contacts of relay 402. Relay 403 does not restore at this time because it is held operated through its upper winding and over conductor 329 in series with the revertive pulse relay 708. 135 At its lower armature, relay 402 shifts the circuit of operating magnet 404 to wiper 410, so that the further operation of magnet 404 is dependent upon the continued supply of ground potential on wiper 410. In this way, the local circuit of 140 operating magnet 404 has been opened responsive to wiper 410 arriving on the first grounded one of six successive contacts, and the time of six steps of magnet 404 is allowed for the consequent above-described operations to take place 145 150

and change over the circuit of magnet 404 to the group-test wiper 410 so as to avoid over-running the first contact in the desired group.

Since the fifty-first set of contacts accessible to wipers 408—411 is not needed, this contact set is unused and the contact thereof in the bank of wiper 410 is grounded, as indicated, causing wipers 408—411 to advance over this contact set also.

10 The wipers of the connector C—1 now come to rest because neither wiper 410, nor the corresponding wiper (414) of the lower wiper set now encounters ground potential. In addition, the circuit through the winding of relay 403 for re-15 vertive-pulse relay 708, Fig. 7, is now open, permitting relays 708 and 403 to restore. When relay 403 restores, it connects operating magnet 404 at its inner-lower armature, through the operated armature 421, and the lower armature of 20 relay 401, to the incoming conductor 332, preparatory to the final positioning (with wipers 412—415 standing on the first contact set in the associated bank, the first set in the sixth consecutive 25 group) of wipers 412—415 on the contacts of the called line.

In the director, when relay 708 now restores, it 30 opens the revertive-control circuit at its upper armature, while at its inner armature it opens the locking circuit of slow-acting series relay 704 and the upper locking circuit of relay 703, so that, in case series relay 802 has fallen back at the end of the units digit and opened the initial circuit of relay 703, relay 702 now energizes in the lower locking circuit in series with relay 703. Its circuit is from ground potential supplied from release-trunk conductor 346, through the lower contacts of relay 702. Upon operating, relay 703 disconnects the revertive-pulse relay 708 at its upper armature; disconnects operating magnets 40 721 and 812 at armatures 731 and 732; opens a further point in the upper locking circuit of relay 703 at armature 733; prepares an impulsive circuit at armature 734 for operating magnet 721, while at an adjacent armature it connects the 45 units interrupter relay 701 to ground by way of the inner-upper armature of relay 709, normally closed contacts controlled by the inner armature of relay 708, inner-upper armature of relay 710 and the inner-upper armature of relay 707, causing relay 701 to operate.

Final positioning of the connector C—1

When relay 701 operates, it closes a circuit for relay 708, whereupon relay 708 operates and at 55 the contacts controlled by its inner-upper armature it opens the circuit of relay 701. Relay 701 shortly restores and opens the circuit of relay 708, whereupon relay 708 restores and again closes the circuit of relay 701. This interaction 60 between relays 701 and 708 continues until the release-control relay 707 is operated through the wiper 723 when the predetermined number of digit impulses has been transmitted to the connector C—1 to bring about the units setting 65 thereof.

Each time relay 708 energizes under the above-described control of the units-interrupter relay 701, it closes a circuit at its inner armature through the middle-upper armature of relay 707, 70 and armature 734 for operating magnet 721 of the register RS—3. Each time relay 701 operates, it closes a circuit for the lower winding of relay 704 and a circuit over wiper 824 for operating magnet 404 of the connector C—1.

75 Series relay 704 operates upon the first of these

operations of relay 701, (in case it has restored) and remains operated throughout the series of impulses delivered to the connector. The circuit for operating magnet 404 includes the lower armature, normal of relay 401, armature 421, and the inner armature of relay 403. Operating magnet 721 energizes and advances wiper 723 each time it receives an impulse, and operating magnet 404, energizes each time it receives an impulse, and it advances the wipers 408—415 one step each time it deenergizes following an im-

80 pulse.

Since the units digit stored on the register switch RS—3 is a 6 wiper 723 has been advanced six steps from its normal position as shown in the drawings. As a result, wiper 723 must be advanced four additional steps to return again to its normal position. Therefore, when the fourth control impulse has been delivered to magnets 721 and 404, wiper 723 is returned to its normal 90 position, whereupon the units-test or release-control relay 707 is energized from ground by way of the grounded conductor 720, the lower armature of relay 710, and the lower armature of relay 702. Upon operating, relay 707 opens an 95 additional point in the circuit of the units-interrupter relay 701 at its inner-upper armature, thereby terminating the series of impulses. When the final impulse (the fourth impulse in the series) is thus terminated, operating magnet 404 100 of the connector C—1 restores and advances the wipers 412—415 from the third set to the fourth set of contacts in the first contact group in the associated lower bank semi-circles. This is the contact group associated with the line of sub- 110 station B, telephone number 1166.

Testing the called line

With slow-acting series relay 704 energized as 115 above pointed out during the final setting operation of the connector C—1, busy relay 705 is connected through the resistance element 714 and the upper armature of series relay 704 and the upper armature of relay 707 (as soon as relay 120 707 operates), to the trunk conductor 329 leading to the connector C—1. In the connector C—1 conductor 329 is now connected through the upper contacts of switching relay 401, inner-upper armature, normal, of relay 403, and the 125 upper winding of switching relay 401, to the test wipers 409 and 413.

The called line busy

When test wiper 413 arrives on the test contact of the called line, at the end of the final 130 impulse in the series, a ground potential is encountered on the test contact of the called line by test wiper 413 in case the called line is busy. In case ground potential is encountered, a circuit 135 is closed through the upper winding of relay 401, as previously traced, through resistance element 714 for the two-step relay 705. Busy relay 705 is operated through its first step to close its lightly adjusted, first-step, lower armature, but 140 the marginally adjusted switching relay 401 is not operated because of the current-limiting effect of resistance element 714.

After a slight interval, relay 704 restores and 145 closes a locking circuit for busy relay 705 at its lower armature to the grounded release trunk conductor 346, while at its inner-upper armature it transfers the test circuit to idle relay 706, which relay is prevented from operating at this time because it is connected so that it requires 150

a potential other than ground potential for its operation.

When its locking circuit is closed, relay 705 energizes fully, and places ground potential on conductor 343 whereupon relay 304, associated with the penultimate selector PU-1, operates through armature 341 and in series with the upper winding of the associated line relay 302. Upon operation, relay 304 opens a point in the circuit of switching relay 308 at its lower armature so as to prevent the connection being switched through to the wipers at this point, and at its upper armature it closes a connection from the common busy-tone lead 350 to the incoming talking conductor 231 by way of the associated small-capacity condenser, thereby causing busy-tone current to be sent back to the calling line to inform the calling subscriber that the called line is in use. At the same time, line relay 302 is energized in series with the lower winding of relay 304 and over conductor 343, bringing about the operation of release relay 303 so as to cause the director DR-1, Figs. 7 and 8, to be returned to common use, as will be pointed out hereinafter.

The called line idle

Assume now that the line at substation B is idle when called. Under this condition, busy relay 705 does not operate, as test wiper 413 of the connector C-1 does not encounter a ground potential on the test conductor of the called line. Then, when series relay 704 falls back and transfers the test circuit from busy relay 705 to idle relay 706, relay 706 operates in series with the cut-off relay of the called line (corresponding to cut-off relay 106 of the line of substation A, Fig. 1). Upon operating, relay 706 at its inner lower armature closes a locking circuit for its lower winding to the grounded release-trunk conductor 346; it places a shunt around its upper winding at its inner-upper armature to permit switching relay 401 of the connector C-1 to operate; at its lower armature it disconnects relay 704 from the lower conductor of the talking circuit so as to clear this conductor for the passage of ringing current, and at its upper armature it places a ground potential on switch-through conductor 344.

Switch-through at the connector

In the connector C-1, switching relay 401 now operates through its upper winding responsive to the self-shunting of relay 706, above described. At its inner-lower armature, switching relay 401 locks itself to ground at armature 422; it prepares a restoring circuit for operating magnet 404 at its middle lower armature; at its inner-upper armature it disconnects the incoming grounded release-trunk conductor from resistance element 406 and connects it by way of the test wiper 413 to the test conductor of the called line, thereby providing a direct guarding ground-connection; and at its upper and lower armatures it extends the incoming conductors 329 and 332 through wipers 412 and 415 to the called line, at the same time disconnecting the incoming conductors from any attachments or bridges in the connector C-1.

Switch-through at the penultimate selector

In the penultimate selector PU-1, when the switching conductor 344 is grounded by the upper armature of idle relay 706 of the director DR-1, line relay 302 is energized through its

upper winding, by way of the middle-upper armature of the operated connecting relay 307, but busy relay 304 is not operated in this case, as when conductor 343 is grounded by busy relay 705 of the director. Upon operating, line relay 302 closes a circuit for release relay 303, whereupon release relay 303 operates and closes a circuit at its inner-lower armature through contacts of ring-cut-off relay 306 for the meter-control relay 305. Meter-control relay 305 now operates preparatory to the metering operation, which is to take place in case the called subscriber responds. Release relay 303 also applies ground potential locally (through the contacts controlled by the upper armature of the meter-control relay 305, its own middle-upper armature, and spring 309) to the incoming release-trunk conductor 233, at the same time disconnecting conductor 233 from the common release-trunk conductor 346; and at its upper and lower armatures it disconnects the incoming line conductors 231-234 from the common line conductor 345 and ground, and connects them through the reversing contacts of the back-bridge relay 301 to the windings of line relay 302, so as to hold line relay 302 operated over the calling line in the usual manner, after the common equipment has become disconnected.

When the inner-lower armature of release relay 303 operates to close a circuit for the meter-control relay 305, it closes a circuit at the same time through contacts of busy relay 304 for the switching relay 308. Switching relay 308 thereupon operates to connect up the ringing circuit to wipers 321 and 324, and to make a multiple ground connection at its inner-lower armature to release-trunk conductor 331 by way of wiper 323.

Signalling the called substation

The signalling of the called substation now takes place, the ringing current being obtained from the common ringing lead 340, whence it flows, by way of the upper winding of ring-cut-off relay 306, and the lower talking conductor of the established connection, to the line of substation B, by way of wiper 415 of the connector C-1. The ringing-return circuit is by way of wiper 412 of the connector C-1 and the upper talking conductor 329, to ground by way of the upper armature of ring-cut-off relay 306.

Clearing out the director DR-1

The way in which the director DR-1 is cleared out following the switching-through operation at the penultimate selector PU-1 will now be pointed out. At this point it may be well to mention that the following relays are now operated in the director DR-1: counting relays 702 and 703, idle relay 706, units-stop or release-control relay 707, hunting-control and tens-cut-off relay 709, the transfer and connector-start relay 710, line and release relays 711 and 801, tens-test relay 803, and switching relay 807.

When the incoming line conductor 231 of the selector PU-1, Fig. 3, is disconnected from common line conductor 345, at the upper armature of release relay 303, line relay 711 in the director DR-1 restores and shunts release relay 801 at the contacts controlled by its inner-upper armature, thereby bringing about an ineffectual, momentary operation of series relay 802. After a slight interval, release relay 801 restores and disconnects the incoming release-trunk conductor 150

- 346 from ground at its inner-lower armature, but it reconnects it to ground at the resting contact of this armature by way of the inner-lower armature of the operated release-control relay 707, 5 thereby maintaining the director guarded for the time being. At its upper armature, relay 801 removes ground potential from conductor 720, thereby opening its previously existing holding circuit, the circuit of series relay 802, and the 10 circuit of switching relay 807. Relay 807 now restores, and relay 802 does so shortly. The removal of ground potential from conductor 720 also opens the circuit through the lower armature of relay 710 and wiper 723 for the lower 15 winding of relay 707. Relay 707, however, remains operated for the time being by way of its upper winding, as will shortly appear. At its lower armature, relay 801 closes a restoring circuit for the register RS-2 by way of off-normal contacts 811 and the self-interrupting contacts 20 of magnet 812. Magnet 812 operates rapidly in a buzzer-like manner to advance wiper 813 to its normal position, whereupon the operating circuit is opened at off-normal contacts 811.
- 25 At armature 831, relay 801 closes a restoring circuit for operating magnet 810 of BPS-3 by way of wiper 825, and it also closes a restoring circuit through the lower armature of the release-control relay 707 and off-normal contacts 30 732 for operating magnet 721 of the register RS-3, in such cases as the call is abandoned before the director has completed its operation. In the present case, the director has completed its operation and the register RS-3 is already 35 in its normal position consequent to the connector C-1 having been finally positioned.
- With the closure of the restoring circuit for the by-pass selector BPS-3 through the restoring wiper 825 and the self-interrupting contacts 40 of magnet 810, magnet 810 starts to operate in a buzzer-like manner to restore the wipers 821-830 to their normal position, wherein wiper 825 passes off the last grounded contact in its bank, and arrives upon the ungrounded fifty-first bank contact, thereby opening the restoring circuit. It is to be noted that a branch circuit exists from wiper 825 by way of the middle-upper armature of relay 808, and the inner-upper armature of 45 release relay 801 for the upper winding of relay 707 during the restoring operation. By this circuit, the release-control relay 707 is maintained operated until the by-pass selector BPS-3 has been restored to its normal position. It is to be noted that relay 707 is a slow-acting relay. As a 50 result, it remains operated for a slight interval after the by-pass selector has returned to its normal position, thereby giving a slight additional time for the register RS-3 to return to its normal position in case it is being restored 55 at a time when the by-pass selector BPS-3 needs to take only a minimum number of steps to reach normal position. This same arrangement, also gives time for the timing switch T-2 to complete its restoration to normal, as well as the register 60 RS-2, before relay 707 restores.
- When relay 707 restores, responsive to wiper 825 reaching the fifty-first associated contact, it disconnects release-trunk conductor 346 from ground at its inner-lower armature and extends 65 it to battery by way of test-jack spring 712 and resistance element 713, thereby marking the associated idle penultimate selectors as idle. At this time, relays 702, 703, 710, 803, and 709 restore, and the clearing out of the director DR-1 is complete.

The called subscriber responds

It will be understood that the ringing current placed on the ringing lead 340 is ordinarily interrupted by a ringing interrupter and that a battery potential is caused to exist on conductor 340 at all times, in accordance with the usual practice. Therefore, when the receiver is removed at substation B and the usual direct-current talking bridge is closed across the conductors of the called line, ring-cut-off relay 306 is operated through its upper winding, whereupon it closes a locking circuit for its lower winding at its inner-lower armature, at the same time opening the circuit of the slow-acting meter-control relay 305. At its upper and lower armatures, relay 306 opens the ringing circuit and completes the talking circuit between the calling and called lines, while at its inner-upper armature it disconnects ground potential from the incoming release-trunk conductor 231 and substitutes a positive battery potential, thereby increasing the current flow over conductor 233 and back over the release-trunk conductor of the established connection, through the meter 107 associated with the line circuit LC of the line of the calling substation A. The meter 107 is now operated responsive to this "booster" battery applied as above pointed out. The operation of the meter assesses a unit charge against the calling line in the usual manner.

Back-bridge relay 301 now operates over the called line and closes a multiple holding circuit at its middle-lower armature for relays 306 and 308, while at its inner armatures it reverses the connections between incoming conductors 231 and 234 and line relay 302, for any desired supervisory purpose.

After a slight interval, meter-control relay 305 restores because it was disconnected, as above-pointed out, at the contacts controlled by the inner-lower armature of relay 306. Upon restoring, relay 305 disconnects the positive battery potential from the incoming conductor 233 and substitutes ground potential again.

The two subscribers may now converse with each other as desired, the conversational path being outlined by the heavy talking conductors.

Releasing the established connection

The way in which the established connection is released will now be pointed out. It will be assumed first that the subscriber at the calling substation A is the first to replace his receiver when the conversation has been terminated, in which case the penultimate selector PU-1 and the connector C-1 are held operated under the control of substation B, while the connection with the line of substation A by way of the switches F, FS, and FS-1 is released.

The calling subscriber hangs up

When the receiver is restored at substation A, line relay 302 restores and opens the circuit of release relay 303, and release relay 303 restores after a slight interval. Since back-bridge relay 301 is now operated over the line of substation B, the restoration of relay 303 does not result in the locking circuits of relays 306 and 308 being opened, but instead a ground potential is extended by way of the middle-lower armature of relay 301 and the inner-lower armature of relay 303 to the common supervisory conductor 362, over which a suitable supervisory signal may be given of the present condition. Re-

150

lay 303 also removes ground potential at its middle-upper armature from the incoming release trunk conductor 233 so as to release the preceding switches, but it does not reconnect conductor 233 to the common release-trunk conductor 346 extending to the equipment of Figs. 7 and 8, because switching relay 308 is maintained operated, as above pointed out.

In the line circuit LC, cut-off relay 106 now falls back, restoring the line circuit to normal condition; in the link circuit including the switches F and SS, relay 115 now falls back and restores the link circuit to normal condition; and in the first selector FS-1, switching relay 201 restores the associated circuit connections to normal.

By the foregoing operations, the connection set up through the switches F, SS, and SF-1 is severed and the switches are available for common use.

The called subscriber hangs up

When the receiver is restored at substation B, back-bridge relay 301 restores, thereby disconnecting supervisory conductor 362 at its lower armature and opening the circuit of relays 306 and 308 at its middle-lower armature. When this occurs, relays 306 and 308 restore, and relay 308 reconnects the incoming release-trunk conductor 233 to the common release-trunk conductor 346, thereby marking the penultimate selector idle.

Relay 308 also removes ground potential from conductor 331 leading to the connector C-1, whereupon transfer relay 402 restores and opens the locking circuit of the lower winding of switching relay 401 at armature 422, but relay 401 remains operated for the time being, as will appear presently. At its lower armature, relay 402 places ground potential by way of the lower armature of the restored relay 403 on all of the normally ungrounded contacts in the bank of wipers 410 and 414, except the fifty-first contact in the bank of wiper 414, thereby closing a self-interrupting circuit through either of these two wipers for operating magnet 404: by way of the normally closed contacts controlled by the lower armature of relay 402, the middle-lower armature of the operated relay 401, and the self-interrupting contacts of magnet 404. A branch holding circuit exists at this time through the middle-upper armatures of relays 403 and 402 for relay 401. Magnet 404 now operates to drive the wipers 408-415 until wiper 414 encounters the ungrounded fifty-first associated bank contact, whereupon the driving operation ceases and relay 401 restores and replaces battery potential on conductor 331 to mark the switch idle.

The connection set up between substations A and B has now been completely released and all of the apparatus involved therein is available for common use.

Releasing when the called subscriber hangs up first

It will now be assumed that the subscriber at substation B is the first to replace his receiver after the conversation between the subscribers at substations A and B. When the receiver is replaced at substation B, back-bridge relay 301 restores and reverses the connections between the incoming conductors 231 and 234 back to normal, at the same time opening the multiple holding circuit of relays 306 and 308. Under this condition, when the subscriber at substation A replaces his receiver and thereby brings about the restoration of relays 302 and 303, relays 307 and 308 restore immediately following the restoration of relay 303, and the connector C-1 is restored to its normal condition as hereinbefore described, responsive to the restoration of relay 308.

Additional explanation

A detailed description of the operation of the apparatus when a typical connection is set up having been given, additional explanation will be made of operations involved under slightly different circumstances. It will be explained first how the revertive control of the connector is accomplished when the number called contains the tens-digit 0.

Handling the tens-digit 0

When the tens-digit received at the register RS-2, Fig. 8, is the digit 0, the wiper 813 is advanced ten steps, so that it passes over all the contacts in its bank and returns again to the marked contact from which it started (the contact marked by the group-test wiper 830 of the by-pass selector BPS-3). Under this condition, when the transfer and connector-start relay 710 operates at the termination of the impulse series constituting the tens digit, relay 803 responds immediately to being connected at armature 736 in the test circuit, in series with the lower winding of the energized relay 805, and wiper 813. At about the same time, operating magnet 812 responds to the closure of its circuit at armature 720 of relay 810 (through the contacts of the revertive-pulse relay 708) and advances wiper 813 one additional step. When this occurs, the de-energization of test-control relay 805 takes place, relay 803 remaining operated because of its locking circuit through its upper winding. The hereinbefore-described operating circuit for the tens cut-off relay 709 is now complete through the lower contacts of relays 803 and 805, and the energization of relay 709 awaits only the operation of relay 708 responsive to the first revertive pulse, and when it takes place the revertive control of the connector is ended, and the wipers of the connector are stopped in association with the first contact in the second consecutive tens group.

Special provisions are made for handling the units digit 0, as will now be described:

Handling the units digit 0

From the description hereinbefore given, it is evident that the number of units impulses transmitted to the connector under the control of the register RS-3 is the complement with respect to 10 of the number of impulses in the units digit received at the register RS-3. Now, when the digit 0 is received at the register RS-3, no complementary impulses are to be transmitted because the digit 0 is represented by ten impulses, and the wiper 723 is, therefore, caused to make a complete revolution and return again to its normal, or cut-off, position. Under this condition, the line desired is the first line in the selected tens group, and the wipers of the connector are already standing upon this line as the result of the tens selection at the connector. It is necessary, therefore, that the operation of the units-cut-off or release-control relay 707 shall follow the operation of relay 702 of the counting pair comprising relays 703 and 702 without any units impulses being transmitted by the units-interrupter relay 701, and that the slow-acting series or test-control relay 704 shall be in an

energized condition when relay 707 operates, so as to enable relay 705 to make the hereinbefore-described busy test of the called line.

Assuming now that the units digit 0 has already been dialled before the connector has been positioned in its tens movement, and, therefore, before tens-cut-off relay 709 has operated, counting relay 703 has already become operated and locked at its upper armature through armatures 733 and 741 to conductor 720, and the initial circuit of relay 703 has been opened by series relay 802, resulting in an immediate operation of relay 702 in series with relay 703 responsive to the operation of armature 741 of tens-cut-off relay 709. Slow-acting series relay 704, which relay it will be recalled first became energized from the grounded conductor 720 through armature 741 upon the seizure of the director, has its circuit opened at armature 741, so that it will shortly restore.

When relay 702 operates, it completes a circuit at its lower armature and through wiper 723 for the lower winding of units-cut-off relay 707, whereupon relay 707 operates and completes the test circuit by way of wiper 821 through the upper armature of the still-operated, slow-releasing relay 704 for the busy-test relay 705. At its inner-upper armature, relay 707 opens the circuit for the units-interrupter relay 701 before relay 701 has had time to operate to start a series of units impulses. The test circuit is switched over from busy relay 705 to idle relay 706 when relay 704 restores.

From this point, the operations are the same as hereinbefore described.

When the tens-positioning or group-setting of the connector has been accomplished before the units digit is dialled, relay 703 has not been operated and relay 702, therefore, cannot operate responsive to the operation of the tens cut-off relay 709, as it does under the conditions above assumed. In this case, the slow-acting relay 704 restores without any busy test being made, as the units cut-off relay 707 is not operated. If, under this condition, the units digit 0 is dialled, series relay 802 at its lower armature closes the hereinbefore-traced circuit (from ground by way of the grounded conductor 720 and the lower armature of the operated relay 710) through the inner-upper armature of relay 702 for relay 703. Relay 703 operates and closes a locking circuit for itself at its lower armature in series with relay 702, while at its upper armature it closes a point in the previously-discussed upper locking circuit. At this time, the upper armature does not close a locking circuit for relay 703 because armature 741 has been operated. The upper winding of relay 704, however, is energized through the upper armature of relay 702 by way of armature 733, whereupon relay 704 operates and prepares to make the usual busy test.

Under this condition, when series relay 802 restores and opens the initial circuit of relay 703, relay 702 energizes in series with relay 703 and connects up the test wiper 723 at its lower armature to enable the units-cut-off relay 707 to energize immediately and prevent the sending out of any units-control impulses. The slow-acting relay 704, being disconnected at armature 733, deenergizes after a sufficient time has elapsed to enable the busy test to be made, and transfers the test circuit to the idle relay 706.

Overflow at the first selectors

75 The operations taking place when an overflow

condition is encountered at a first selector, the first selector FS-1 for example, will now be described. For this purpose it will be assumed that the first selector FS-1 has been seized and that the by-pass selector BPS-1 is unable to find an idle trunk in the selected group. Under this condition, neither wiper-switching relay 609 nor switching relay 608 can operate through their respective test wipers 618 and 614. As a result, group-test relay 604 is deenergized because group-test wiper 620 passes off the last contact in the group in which the wipers of the by-pass selector are searching. As a result, group-test relay 604 opens the driving circuit previously existing for magnet 610 at its upper armature and completes a restoring circuit for magnet 610 by way of the resting contact at the upper armature of relay 604, middle-upper armature, normal, of relay 602, and wiper 613, to ground through the associated bank contacts. At the same time, relay 604 closes a circuit through the lower winding of relay 602 in series with operating magnet 610, but relay 602 does not operate for the time being because it is short-circuited by the restoring circuit of magnet 610 until the by-pass selector has been restored to its normal position.

When the by-pass selector reaches its normal position, wiper 613 opens the restoring circuit when it arrives upon its ungrounded normal contact, whereupon the lower winding of relay 602 is energized in the following circuit: from ground by way of the grounded conductor 629 (grounded at the middle-upper armature of release relay 603), armature 623 of relay 601, upper armature, normal, of relay 605, inner-lower armature, normal, of group-test relay 604, lower winding of relay 602, middle-upper armature of relay 602, upper armature of group-test relay 604, and contacts 653 and 657, to battery by way of operating magnet 610. Operating magnet 610 does not operate at this time in series with relay 602 because of the high resistance of the lower winding of the relay.

Upon operating, relay 602 closes a locking circuit for its upper winding at its inner-upper armature by way of armature 624 of relay 601; prepares a new test circuit for relays 608 and 609 at its inner-lower armature; disconnects operating magnet 642 at its lower armature so as to avoid further operation of this magnet in case the calling subscriber should again dial before the operations now taking place have been completed; disconnects the idle-indicating battery potential from the resting contacts of the upper armature of release relay 603 at its upper armature, and at its middle-upper armature it completes a new driving circuit for operating magnet 610 to drive the wipers 611-620 in search of an idle overflow trunk. This driving circuit is from ground by way of the grounded conductor 629, through the middle-upper armature of relay 602, upper armature of group-test relay 604, and through armatures 653 and 657, to operating magnet 610. The wipers 611-620 are now advanced until an idle trunk line is found, not being advanced at all, however, if one of the two overflow trunk lines connected to the normal-position contacts is idle.

It is proposed to connect two overflow trunks to the normal position contacts of the by-pass selector BPS-1, one trunk to the normal position contacts of wipers 611, 612, 614, and 615, and the other to the corresponding contacts of wipers 616-619. These trunks are, of course,

80

85

90

95

100

105

110

115

120

125

130

135

140

145

150

connected to the corresponding contacts in the banks of the conversational switches and the by-pass selector BPS-2, and they may be multiplied, as regards the line and release-trunk conductors thereof throughout as many shelves of selectors as may prove to be desirable. If more overflow trunks are needed, they are obtained by removing as many of the pairs of trunks from the first group as desired. For example, if the first 10 pair of trunks in the first group is to be changed over to overflow working, the first off-normal contact in the bank of wiper 620 is disconnected from the conductor of the first group extending from the bank of the register RS-1, causing the 15 wipers of the by-pass selector to pass over the first pair of trunk lines in the first group when the digit 1 is dialled.

Each of the overflow trunks is assumed to terminate in a trunk circuit as illustrated in Fig. 9. 20 For the purpose of the description, it will be assumed that the overflow trunk accessible to wipers 616-619, Fig. 6, in the normal position of the by-pass selector is idle and that this trunk line is the one terminating in the particular trunk 25 circuit illustrated in Fig. 9. The idle condition of this overflow trunk line is indicated by the connection of battery potential to release trunk conductor 905 through the resistance element 903. Wiper-switching relay 609, therefore, operates through wiper 618, the inner-lower contacts of switching relay 608, middle-lower armature of series relay 605, the operated inner-lower armature of relay 639, inner-lower armature of relay 604, upper armature of series relay 605, 35 armature 623, and the middle-upper armature of release relay 603. Upon operating, relay 609 at its inner-upper armature disconnects the test wiper 614 of the upper set and substitutes the test wiper 618 of the lower set, whereby wiper-switching relay 608 is enabled to energize over the release-trunk conductor 905 in parallel with relay 609; it opens the driving circuit at armature 657, at armatures 655 and 656 it substitutes wipers 616 and 617 for wipers 611 and 612; and 40 at its lower armature it substitutes position-test wiper 619 for position-test wiper 615. Relay 608, upon operating, causes the connection to be switched through to the overflow trunk in the hereinbefore described manner, whereupon the 45 driving circuit for magnet 203 of the first selector FS-1 is completed over conductor 226, causing the first selector FS-1 to assume the position in which the now-selected trunk line terminates in its bank, in the manner hereinbefore 50 described.

When the overflow trunk comprising conductors 904-906 is seized, line relay 901 operates and closes a circuit for release relay 902, whereupon release relay 902 substitutes ground potential on conductor 905 for battery potential, at the same time connecting the busy-tone lead 907 to conductor 906 so as to signal the calling subscriber that a busy or overflow condition is encountered.

When the calling subscriber replaces his receiver responsive to the busy-tone signal, relays 901 and 902 restore, permitting the established reconnection to clear out as hereinbefore described.

Overflow at the penultimate selectors

The way an overflow condition is handled at the penultimate selectors will now be pointed out. For this purpose it may be assumed that the penultimate selector PU-1 has been taken for use, and that the by-pass selector BPS-3,

Fig. 8, is unable to find an idle trunk line in the selected group. Under this condition, the group-test relay 804, which has become energized prior to the restoration of series relay 802, and responsive to the group-test wiper 830 of the by-pass selector arriving on the contact group desired, falls back as soon as wiper 830 has rotated off the last contact in the desired group. Upon restoring, group-test relay 804 closes a circuit from ground by way of the grounded conductor 720, 80 by way of armature 742, operated, inner-upper armature, normal, of series relay 802, middle-upper armature of group-test relay 804, and armature 833, normal, of switching relay 807, for busy relay 705. Busy relay 705 now operates 85 and at its upper armature places ground potential on the busy switching conductor 343, resulting in the energization of busy relay 304 of the penultimate selector PU-1 in series with line relay 302. Busy relay 304 operates to cause busy-tone current from conductor 350 to be returned to the calling line, while line relay 302 operates to cause the hereinbefore-described freeing of the director DR-1.

Concurrent positioning within a shelf

As hereinbefore mentioned, arrangements are provided so that a selector being positioned under control of one by-pass selector of a shelf will not be influenced by the other by-pass of the same shelf, and no interference results in case two selectors on the same shelf are being concurrently positioned by the two by-pass selectors, respectively. Referring now to Figs. 2 and 6, and assuming that the by-pass selectors BPS-1 and BPS-2 are in use in connection with the first selectors FS-1 and FS-2, respectively, it is to be noted that the position-test relay 607 in the by-pass selector BPS-1 is connected to the free pole of the exchange battery, rendering it responsive to a ground potential but not to a battery potential, while the corresponding relay 607' of the by-pass selector BPS-2 is connected to the grounded pole of the exchange battery, rendering it responsive to a battery potential but 105 not to a ground potential. In line with this arrangement, the selector FS-1, (in common with the other selectors associated with the by-pass selector BPS-1) is arranged to apply a ground potential (through resistance element 272, contacts of connecting relay 202, and wipers 205 and 209) during its positioning operation, which ground potential is effective to operate the position-test relay 607 of the by-pass selector BPS-1, but not the corresponding relay 607' of the by-pass selector BPS-2. Similarly, the battery potential applied by the first selector FS-2 (in common with the other first selectors associated with the by-pass selector BPS-2) is effective to operate the ground-connected, position-test relay 115 697' of the by-pass selector BPS-2, but not the battery-connected, position-test relay 607 of the by-pass selector BPS-1.

It is to be noted that a similar distinction is maintained between the position-test relays 806 and 806' of the directors DR-1 and DR-2, Figs. 7 and 8, and the actuating circuits for these relays, controlled by selectors such as PU-1 and PU-2, Fig. 3.

Delayed dialling

Timing arrangements have been provided for freeing the by-pass equipment and returning it to common use in case the subscriber fails to dial the necessary digit or digits following its seizure. 150

Supervising the apparatus

The way in which this result is accomplished will now be pointed out:

Delayed dialling at a first selector

Assuming now that the first selector FS-1, Fig. 2, has been taken for use and that the calling subscriber has failed to dial the first digit within a reasonable time, the timing switch TS-1, Fig. 6, operates in a manner to be now explained to cause the by-pass selector BPS-1 to be returned to common use.

It is to be noted that release relay 603, upon responding when the by-pass selector is taken for use, opens a point in the restoring circuit of the timing switch TS-1 at its inner-lower armature, while at its lower armature it connects the common time-pulse lead 630 to the operating magnet 634 of the timing switch TS-1. A suitable interrupter is provided to place a ground potential on conductor 630 momentarily at the desired intervals, every two or three seconds for example. Each time conductor 630 is thus grounded, operating magnet 634 responds and advances the wiper 633 one step in a clockwise direction. In the normal operation, the by-pass selector BPS-1 has finished its operation before the timing switch TS-1 has advanced far enough to exercise any control. In case the dialling does not start for several seconds, however, wiper 633 advances a sufficient distance to operate relay 601.

When relay 601 operates, it disconnects the upper winding of relay 602 from the restoring wiper 613 of the by-pass selector, at the same time preparing a locking circuit for relay 602; and at armature 623 it closes a point in the stepping circuit of operating magnet 610. At this time, however, series relay 605 is not in operated position and the stepping circuit is not complete. Instead, a circuit for the lower winding of relay 602 is completed through the upper armature, normal, of relay 605, the inner-lower armature, normal, of relay 604, the lower winding of relay 602, middle-upper armature of relay 602, upper armature of group-test relay 604, and armatures 653 and 657, to battery by way of operating magnet 610. Relay 602 now operates and at its inner-lower armature prepares test circuits for relays 608 and 609 to enable the by-pass selector to seize an overflow trunk as hereinbefore pointed out. From this point, the operation takes place as described in connection with an overflow condition.

Delayed dialling at the director DR-1

In case the director DR-1 is taken for use (by way of the penultimate selector PU-1, Fig. 3 for example) and there is an undue delay prior to the dialling of the third of the three digits required to complete the connection, the timing switch TS-2 operates to return the director DR-1 to common use, as will now be described:

When release relay 801 operates responsive to the seizure of the director DR-1, it connects the common time-pulse lead at armature 832 to operating magnet 725 of the timer TS-2. Magnet 725 is operated intermittently over the time-pulse lead to advance the wiper 724 step-by-step in a clockwise direction. In case the operation of the director DR-1 has not been completed in the regularly allotted time, wiper 724 is eventually advanced sufficiently far to close a circuit for busy relay 705. Busy relay 705 thereupon operates and causes the director DR-1 to be freed as explained in connection with the handling of an overflow condition.

From time to time it is desirable to "supervise" the various groups of switching apparatus in order to obtain a momentary indication of the amount of traffic being handled by the several apparatus groups. For this purpose, each of the finder-secondary links, such as the one shown in Fig. 1, is provided with a supervisory lamp, such as the supervisory lamp 117. Ordinarily, these lamps are not lighted when the links are in use. However, when it is desired to supervise the finder-secondary links, the common key 118 is operated, thereby completing a circuit for the supervisory lamp (such as 117) of each busy finder-secondary link. For a similar purpose, the individual lamp 214 and common key 213 are provided, as are the similar keys and lamps associated with the other pieces of switching equipment, as illustrated.

What is claimed is:

1. In a telephone system, a group of lines, a group of trunk lines over which connections from said lines may be extended, a group of links interposed between said lines and said trunk lines, a distributor common to said link circuits, means responsive to a calling condition on any one of said lines for operating said distributor to connect with an idle one of said link circuits, switching mechanism thereupon operable under the control of said distributor for connecting said link circuit with an idle one of said trunk lines, and means responsive thereto and also controlled from said distributor for thereafter associating said link circuit with the calling line and for connecting the calling line with the said idle trunk line by way of said link circuit.

2. In a telephone system, a group of lines, a group of link circuits interposed between said lines and said trunk line, each of said link circuits terminating in a finder having access to said lines and in a secondary switch having access to trunk lines over which calls from said lines may be extended, a distributor common to said link circuits and having access to all of them, means responsive to a calling condition of any one of said lines for operating said distributor to find an idle link circuit, means thereupon effective for operating the secondary switch of the idle link circuit into association with an idle trunk line, and means responsive to an idle trunk line being found for starting the finder switch in which said link circuit terminates in search of the calling line.

3. In a telephone system, a group of lines, a group of link circuits interposed between said lines and said trunk lines, each of said link circuits terminating in a finder having access to said lines and in a secondary switch having access to trunk lines over which calls from said lines may be extended, a distributor common to said link circuits and having access to all of them, means responsive to a calling condition of any one of said lines for operating said distributor to find an idle link circuit, means thereupon effective for operating the secondary switch of the idle link circuit into association with an idle trunk line, means responsive to an idle trunk line being found for starting the finder switch in which said link circuit terminates in search of the calling line, and means responsive to the calling line being located by said finder switch for connecting said finder switch and said secondary switch together to complete a connection from the calling line to said idle trunk line.

4. In a telephone system, a group of lines, finders having access to said group of lines, a pair of distributors, means responsive to a calling condition of one of said lines for operating both of 5 said distributors, each distributor responsive when operated to select an idle one of said finders and to start it in search of said calling line, and means in each distributor effective when it finds an idle finder for rendering said finder busy to 10 the other distributor. 80
5. In a telephone system, link circuits having access to trunk groups, respectively, a pair of distributors each having access to all of said link circuits and each effective to control the operation 15 of any one of said link circuits, each of said distributors having a test wiper to test said links to determine whether or not the other distributor is associated with a link being tested, a second test wiper to determine whether or not the link 20 being tested is idle, a third test wiper to determine whether or not the trunk group accessible to the link circuit being tested is idle, and means controlled by all three of said test wipers of a distributor for causing the distributor to advance 25 until it reaches an idle link circuit associated with an idle group and not associated with the other distributor. 85
6. In a telephone system, a group of lines, trunk lines over which connections may be extended from said lines, a group of link circuits interposed between said lines and said trunk lines and having switching equipment associated therewith for connecting a link circuit with an idle trunk line and with a calling line, a pair 30 of distributors each having access to all of said link circuits and operative to control the switching equipment associated with the link circuits to extend connections from calling lines to said trunk lines, means responsive to a calling condition 35 on one of said lines for causing each of said distributors to select an idle link circuit and to connect such link circuit with an idle trunk and with the calling line, and means responsive to the first connection made with a calling line 40 under the control of one of the distributors for preventing a second connection from being made with said calling line under the control of the other distributor, whereby if a second line is in a calling condition simultaneously the other distributor makes connection between the second line and an idle one of said trunk lines by way 45 of second link circuit. 90
7. In a telephone system, a switching stage comprising a group of selectors having access to a group of trunk lines, a by-pass selector also having access to said group of trunk lines, means for taking any one of said selectors and said by-pass selector for use, means for thereupon directing said by-pass selector to an idle one of 50 said trunk lines, and for making connection with such trunk line by way of the by-pass selector, and means thereupon effective for operating the said selector which has been taken for use to connect with the same trunk line with which 55 connection has been made by the by-pass selector and for substituting the said selector for said by-pass selector. 95
8. In an automatic telephone system, group selectors having access to trunk lines divided into groups, a by-pass selector having access to all of said trunk lines and available for the common use of said group selectors, means responsive to any one of said selectors being taken into use for rendering said by-pass selector temporarily 60 individual to said group selector, means then effective for operating said by-pass selector into association with a desired group of said trunk lines and for causing it to select an idle trunk line in the group, means for marking the selected trunk line, means for operating said group selector to make connection with the marked trunk line, and means thereupon effective for causing the group selector to be substituted for the by-pass selector and for causing the by-pass selector to be returned to common use. 100
9. In an automatic telephone system, a by-pass selector associated in common with a group of selectors, means for taking any group selector in use and for rendering the common by-pass selector temporarily individual to such group selector, means in the by-pass selector responsive to the next digit dialled for selecting the corresponding group of trunk lines and for then making connection with an idle trunk line in the selected group whereby the next digit dialled 105 is transmitted to the next switching stage, means for marking the trunk taken for use by the by-pass selector and for operating the group selector into engagement with a marked trunk, and means thereupon effective for substituting the group 110 selector in the established connection for the by-pass selector and for returning the by-pass selector to common use. 115
10. In an automatic telephone system, a switching stage including a by-pass selector common 110 to a group of group selectors, each of said group selectors and the by-pass selector being of the rotary type of switch having movement in one plane only and each having two groups of wipers, the wipers of the by-pass selector being capable of engaging two trunk lines simultaneously and having wiper-switching means for selecting one group to the exclusion of the other, whereby the trunk lines of a group are accessible 115 to the by-pass selector in pairs, means for associating said by-pass selector with a desired group of trunk lines and for operating it to make connection with a pair of such trunk lines containing at least one idle trunk line, said wiper-switching means being then effective to select one or the other of the wiper sets depending upon the busy or idle condition of the trunk lines in the selected pair, whereby only one trunk line is connected with, said group selectors having their wipers divided into two multiply connected wiper sets, with the two wiper sets located so that only one wiper set at a time makes contact with the switch bank, means associated with the by-pass selector for marking the seized trunk line, and means for rotating the wipers of 120 the associated group selector until the wiper set corresponding to the one in use at the by-pass selector is brought into engagement with the marked trunk line. 125
11. In an automatic telephone system, a switching stage including a by-pass selector common to a group of group selectors, each of said group selectors and the by-pass selector being of the rotary type of switch having movement in one plane only and each having two groups of 130 wipers, the wipers of the by-pass selector being capable of engaging two trunk lines simultaneously and having wiper-switching means for selecting one group to the exclusion of the other, whereby the trunk lines of a group are accessible 135 to the by-pass selector in pairs, means for associating said by-pass selector with a desired group of trunk lines and for operating it to make connection with a pair of such trunk lines containing at least one idle trunk line, said wiper- 140
- 75

- switching means being then effective to select one or the other of the wiper sets depending upon the busy or idle condition of the trunk lines in the selected pair, whereby only one trunk line 5 is connected with, said group selectors having their wipers divided into two multiply connected wiper sets, with the two wiper sets located so that only one wiper set at a time makes contact with the switch bank, means associated with the by-pass selector for marking the seized trunk line, means for rotating the wipers of the associated group selector until the wiper set corresponding to the one in use at the by-pass selector is brought into engagement with the marked trunk 10 line, and means thereupon effective for substituting the group selector for the by-pass selector. 15 12. In a telephone system, a switching stage comprising group selectors and a common by-pass selector, all of said selectors having access 20 to groups of outgoing trunk lines, a trunk line incoming to each of said group selectors, means for operating said by-pass selector to extend a connection from the incoming conductors of any one of said group selectors to an idle trunk line 25 in any desired outgoing group, and means thereupon effective for operating the concerned group selector to make connection with the same trunk line connected with by the by-pass selector and for then serving the connection made by way of 30 the by-pass selector. 13. In an automatic telephone system, a switching stage comprising selectors and a common by-pass selector, each of said group selectors being composed of a rotary type switching mechanism having two multiply connected wiper sets positioned so that only one set at a time is rotated over the contact bank, said by-pass selector being composed of a similar switching mechanism with the wipers divided into two alternative sets so positioned that both sets are simultaneously driven over the contact bank, and means including bank-multiple connections between the group selectors and the by-pass selector whereby the by-pass selector may be operated 40 at a rapid rate over the bank contacts to make temporary connection between the incoming conductors of any group selector and any desired trunk line. 45 14. In a telephone system, a switching stage including group selectors and a common by-pass selector, two wiper sets in said by-pass selector, means effective whenever any one of said group selectors is to be operated to connect with an idle trunk line in a desired group for operating both 50 wiper sets of the by-pass selector over the contact bank simultaneously whereby connection is quickly made with the desired trunk line, and means thereafter effective for rotating the two wiper sets of the concerned group selector over the contact bank successively until connection is made with the same trunk line connected with by the by-pass selector. 60 15. In a telephone system, a switching stage including group selectors and a common by-pass selector, two wiper sets in said by-pass selector, means effective whenever any one of said group selectors is to be operated to connect with an idle trunk line in a desired group for operating both 65 wiper sets of the by-pass selector over the contact bank simultaneously whereby connection is quickly made with the desired trunk line, means thereby effective for rotating the two wiper sets of the concerned group selector over the contact bank successively until connection is made with the same trunk line connected with by the by- 70 75 pass selector, and means thereupon effective for substituting the wipers of the group selector for the wipers of the by-pass selector. 16. In combination, group selectors and a by-pass selector, each group selector having two multiply connected sets of wipers, said by-pass selector having two alternative sets of wipers together with means for selectively connecting them for effective operation, conductors incoming to each of said group selectors, means for operating the wipers of said by-pass selector simultaneously to search for an idle trunk line in a desired group and for connecting the incoming conductors of any desired group selector with the found idle trunk by way of the associated one of the wiper sets of the by-pass selector, and means thereupon effective for operating the two wiper sets of the concerned group selector over the contact bank successively, and means effective when the trunk line with which connection has been made by the wipers of the by-pass selector is located for stopping the operation of the group selector and for thereupon substituting the instant effective wiper set of the group selector for the selected wiper set of the by-pass selector. 90 95 17. In a telephone system, a switching stage comprising a group of selectors and an apparatus unit common to said selector group, a trunk line incoming to each selector, a common line relay in said common apparatus unit to which all of 100 said incoming trunk lines extend, a connecting relay in each of said selectors having a winding connected in series with one of the associated incoming conductors, whereby said connecting relay operates when the associated selector is seized and connects up the common apparatus unit for 105 operation with the selector. 18. In a telephone system, a selector switch having access to lines divided into groups, means for marking contacts in the bank of said selector 110 to predetermine a group of trunk lines, a group-test relay in said selector, means for operating said selector over the contacts in its bank, circuit connections for operating said group-test relay to terminate the group-hunting movement when 115 the first of the marked contacts is reached, means responsive to the operation of said group-test relay for causing said selector to rotate over the lines in the selected group in search of an idle 120 trunk line, means including the marked contacts for maintaining said group-test relay operated as long as the wipers of the selector are searching within the predetermined group, and means responsive to the restoration of said group-test relay when the wipers are rotated beyond a predetermined group for transmitting a busy signal 125 to the calling party. 130 19. In a telephone system, a selector switch having access to lines divided into groups, means for marking contacts in the bank of said selector 135 to predetermine a group of trunk lines, a group-test relay in said selector, means for operating said selector over the contacts in its bank, circuit connections for operating said group-test relay to terminate the group-hunting movement when 140 the first of the marked contacts is reached, means responsive to the operation of said group-test relay for causing said selector to rotate over the lines in the selected group in search of an idle trunk line, means including the marked contacts for maintaining said group-test relay operated as long as the wipers of the selector are searching within the predetermined group, and means responsive to the deenergization of said group-test 145 relay when the selector advances beyond the pre- 150

- determined group for terminating the trunk testing operation of the selector.
20. In a telephone system, a selector switch having access to lines divided into groups, means for marking contacts in the bank of said selector to predetermine a group of trunk lines, a group-test relay in said selector, means for operating said selector over the contacts in its bank, circuit connections for operating said group-test relay 5 to terminate the group-hunting movement when the first of the marked contacts is reached, means responsive to the operation of said group-test relay for causing said selector to rotate over the lines in the selected group in search of an idle 10 trunk line, means including the marked contacts for maintaining said group-test relay operated as long as the wipers of the selector are searching within the predetermined group, and means responsive to the deenergization of said group-test 15 relay when the selector reaches the end of the predetermined group for preventing said selector from seizing an idle trunk in a succeeding group.
21. In a selector having access to lines divided 20 into groups, a marking switch and means for positioning it responsive to a series of impulses to predetermine a desired group of lines, an impulse-controlled relay and means for causing it to operate at the termination of the impulse series to start said selector to searching for an idle line, means for advancing said selector to the predetermined group marked by said marking switch, and means for preventing the said operation of said relay until said selector has reached 25 the predetermined group.
22. In a selector having access to groups of lines, a marking switch and means for operating it responsive to a train of impulses to mark a corresponding group of lines, means for advancing said selector to the marked group, a slow-acting relay associated with said marking switch, means for supplying impulses of current to said relay for operating it and for maintaining it operated as long as impulses are being received by 30 said marking switch, means for supplying a reduced current to said relay following the termination of the final impulse of the series until said selector has been advanced to the marked group, and means responsive to the restoration of said 35 relay for starting said selector to hunting for an idle line in the marked group.
23. In a selector having access to lines divided 40 into groups, means responsive to a received series of impulses for predetermining a group of lines, a relay in said selector and means for operating said relay and for maintaining it operated as a slow-acting relay during the received impulse series, means effective responsive to the first impulse of the series for closing a holding 45 circuit for said relay for maintaining it operated after the impulse series has terminated, means for driving said selector into association with the marked group, and means responsive to said selector coming into association with the marked 50 group for opening said holding circuit.
24. In a selector having access to lines divided 55 into groups, means responsive to a received series of impulses for predetermining a group of lines, a relay in said selector and means for operating said relay and for maintaining it operated as a slow-acting relay during the received impulse series, means effective responsive to the first impulse of the series for closing a holding 60 circuit for said relay for maintaining it operated after the impulse series has terminated, means for driving said selector into association with the marked group, and means responsive to said selector coming into association with the marked 65 group for opening said holding circuit.
25. In a selector having access to groups of lines, means for predetermining a desired group of lines and for advancing said selector to the predetermined group, means for causing said selector to search for an idle line in the predetermined group, means effective in case the selector is unable to find an idle line in the predetermined group for terminating the testing operation and for advancing said selector to its normal position, an overflow relay and means for operating it responsive to said selector attaining its normal 70 position under the stated condition, overflow circuits accessible to said selector in its normal position, and means responsive to the said operation of said overflow relay for causing said selector to make connection with one of said overflow 75 circuits.
26. In a selector having access to lines divided into groups, means responsive to a received series of impulses for predetermining a group of lines, a release-control relay and means for operating it responsive to the beginning of a received series of impulses, means effective under this condition for causing the selector to advance until it reaches the predetermined group at the end of a series of impulses and for causing it to search 80 for an idle trunk line in the predetermined group, timing means effective to operate said relay in case the impulse series is not received within a predetermined time, overflow circuits accessible to said selector, and means responsive to the operation of said release-control relay under the last-named condition for operating said selector to make connection with an idle one of said overflow 85 circuits.
27. In a selector having access to lines divided 90 into groups, means responsive to a received series of impulses for predetermining a group of lines, a release-control relay and means for operating it responsive to the beginning of a received series of impulses, means effective under this condition 95 for causing the selector to advance until it reaches the predetermined group at the end of a series of impulses and for causing it to search for an idle trunk line in the predetermined group, timing means effective to operate said relay in case the impulse series is not received within a predetermined time, and means responsive to the operation of said release-control relay under the last-named condition for transmitting a busy 100 signal to the calling subscriber.
28. In combination, a conversational selector and a by-pass selector having common access to trunk lines divided into groups, means for associating the by-pass selector with a desired one of said groups and for operating it to select an idle 105 trunk line in the group, means thereupon effective for closing a driving circuit for said conversational selector to bring it into association with said trunks successively, and means in the by-pass selector responsive to said conversational 110 selector arriving on the said idle trunk for opening said driving circuit and for restoring said by-pass selector to common use.
29. In combination, a register sender, a connector operable under the control of said register 115

sender to execute two movements to come into a desired position, means associated with said connector for transmitting revertive-control impulses to said register sender during the first movement of said connector, and means in the register sender for transmitting directive impulses to said connector during the second movement thereof.

30. In combination, a connector operable in two movements to come into a desired position, means in the connector effective during the first movement for generating revertive-control impulses, and means external to said connector and effective during the second movement thereof for delivering directive impulses to said connector.

31. In a telephone system, an automatic switch arranged to be brought into a desired position by two successive movements, means for causing said switch to operate as a hunting switch to execute the first movement, and means for delivering directive impulses to said switch to cause it to execute the second movement.

32. In a telephone system, a director including a by-pass selector and associated with switches at a switching stage, said by-pass selector having its bank contacts multiply connected with the bank contacts of said conversational switches, means for taking said director for use by way of any one of said conversational switches and for operating said by-pass selector to select an idle trunk line in a desired group leading to the next rank of switches, means controlled by the setting of the by-pass selector for positioning the conversational switch on the same trunk line, and means controlled by said director for positioning the switch to which the seized idle trunk extends.

33. In an automatic telephone system, a directing device associated with an intermediate switching stage, means controlled from said directing device for positioning switches at said intermediate stage by hunting movement of the switch being positioned, and means controlled from said directing device for directly positioning switches in the succeeding stage.

34. In combination, a register, means for delivering a series of setting impulses to said register to set it in a desired position, hunting means effective to hunt for and mark the assumed position of said register, the said setting means being again effective responsive to a further series of impulses for imparting a second setting to said register with respect to said marked position, and means dependent upon the last-named setting for delivering a series of impulses of corresponding value.

35. In a telephone system wherein connections are set up through serially related automatic switches under the control of a register sender, a register in said register sender, means for setting said register sender twice responsive to two series of impulses in a single call, respectively, and means for positioning first one and then a second one of said automatic switches in series in accordance with the two settings, respectively, of said register to complete a single telephone connection.

36. In an automatic telephone system, first and second switching stages, a register and means for twice setting said register responsive to two series of impulses, respectively, for a single telephone connection, means for positioning an automatic switch at said first switching stage in accordance with the first setting of said register, and means for positioning an automatic switch

at the next succeeding switching stage in accordance with the second setting of said register.

37. In an automatic telephone system, two switching stages, a register, means for setting said register responsive to a first series of impulses by imparting a movement to it to move it from a normal position and for again setting said register responsive to a subsequent series of impulses by moving said register from its first assumed position into a position depending upon the number of impulses in the second series, a hunting switch at the first switching stage having access to the trunk groups extending to the next succeeding switching stages, means for driving said hunting switch in a hunting movement until it reaches a position corresponding to the first position attained by said register, means associated with the said hunting switch for causing it to thereupon hunt for and seize an idle trunk line extending to a switch in the second switching stage, means effective to advance said register a third time until it again reaches the position attained at the end of its first movement, and means for positioning the seized switch in the second switching stage in accordance with the number of steps required to be taken by said register in its third movement to reach the position reached at the end of the first movement.

38. In a telephone system, final selectors having access to lines divided into groups and having one movement to reach a desired group and another movement to reach a desired line in the desired group, said final selectors being divided into groups and being accessible to penultimate selectors, a director responsive to three incoming series of impulses, first and second registers in said director, means for delivering the first two of said incoming impulse series to the first register and for delivering the third incoming series to the second register, means controlled in accordance with the position assumed by said first register responsive for the first series of impulses for associating said penultimate selector with the corresponding group of final selectors, whereby the penultimate selector is enabled to search for and seize an idle final selector in the indicated group, means for positioning the seized final selector on a desired group of lines in accordance with the setting of said register responsive to the second series of said impulses, and means for positioning the final selector on the desired line in the desired group in accordance with the setting of the second register.

39. In an automatic telephone system, a trunk line incoming to a group selector, said group selector being of the type which advances its wipers over the contact groups successively, means controlled over said incoming trunk line for marking a desired group in the bank of said selector, means for causing said selector to hunt for the marked group, means effective when the marked group is reached for causing said selector to hunt for an idle line in the marked group, a busy relay associated with said incoming trunk line, and means effective when said group selector is unable to find an idle contact set in the marked group and responsive to the wipers of the selector passing off the last contact set in the marked group for thereupon operating said busy relay.

40. In an automatic telephone system, a trunk line incoming to a group selector, said group selector being of the type which advances its wipers over the contact groups successively, means controlled over said incoming trunk line

for marking a desired group in the bank of said selector, means for causing said selector to hunt for the marked group, means effective when the marked group is reached for causing said selector to hunt for an idle line in the marked group, a busy relay associated with said incoming trunk line, means effective when said group selector is unable to find an idle contact set in the marked group and responsive to the wipers of the selector 5 passing off the last contact set in the marked group for thereupon operating said busy relay, and means controlled by said busy relay for terminating the hunting movement of said selector and for transmitting a busy signal to the calling party.

41. In combination, an automatic switch having its bank contacts divided into groups and having wipers operable to rotate over said groups successively, a controlling device, means in the 10 controlling device for predetermining a desired

group of contacts in the bank of said automatic switch, means for closing a driving circuit for said switch to drive it over the contact groups successively, means controlled by a wiper of said switch for transmitting a control impulse to said control device each time it is passing over an intermediate portion of a contact group, means effective responsive to the received control impulse when the switch is passing over the intermediate portion of the contact group just preceding the desired group for opening said driving circuit and for closing a new driving circuit for said switch, and means for continuing the driving operation of said switch over the driving circuit until the desired group is reached, said new driving circuit including a wiper of said switch and the remaining contacts in the bank of the said wiper in the group just preceding the desired contact group.
